UNITED STATES PATENT OFFICE.

WALTER D. BUTZ, OF NORRISTOWN, PENNSYLVANIA, ASSIGNOR TO THE KILBOURN KNITTING MACHINE COMPANY, OF NEW BRUNSWICK, NEW JERSEY, A CORPORATION OF NEW JERSEY.

MACHINE FOR RUNNING ON KNITTED WEBS.

1,035,081.

Specification of Letters Patent.

Patented Aug. 6, 1912.

Application filed July 9, 1908. Serial No. 442,705.

To all whom it may concern:

Be it known that I, WALTER D. BUTZ, a citizen of the United States, residing in Norristown, Pennsylvania, have invented 5 certain Improvements in Machines for Running on Knitted Webs, of which the following is a specification.

My invention consists of certain improvements in the machine for running on knitted 10 fabric for which I obtained Letters Patent No. 670,308, dated March 19, 1901.

The present machine, while similar in its 15 general operation to that forming the subject of my former patent, embodies many changes in the construction and operation 20 of those parts which it possesses in common with the former machine, and also many added parts, the general purpose of the present invention being to facilitate and perfect the operation of the machine.

The novel features of construction of the 25 present machine, the novel functions performed thereby, and the manner in which such functions are performed will be fully 30 set forth hereinafter, and the various novel constructions and combinations of parts which I have devised will be specifically 35 embodied in the claims.

In the drawings Figure 1 is a side view 30 of part of the machine; Fig. 1^a is a view partly in elevation and partly in section, of another part of the same; Fig. 2 is a top or plan view of that part of the machine shown in Fig. 1; Fig. 3 is a central vertical section of part of the machine; Fig. 4 is a central vertical section of another part of the machine which coöperates with that illustrated in Fig. 3; Fig. 5 is a central vertical section illustrating parts of the machine shown in Figs. 3 and 4, certain of 40 these parts however bearing a different relation to each other from that shown in Fig. 3; Fig. 6 is a transverse section on the line *a*—*a*, Fig. 5; Fig. 7 is a transverse section on the line *b*—*b*, Fig. 3; Fig. 8 is a view partly in elevation and partly in transverse section on the line *c*—*c*, Fig. 4; Fig. 9 is a transverse section on the line *d*—*d*, Fig. 4; Fig. 10 is a transverse section on the line 45 *e*—*e*, Fig. 3; Fig. 11 is a central vertical section showing some of the parts in a more

advanced position than that represented in Fig. 5; Fig. 12 is a view partly in side elevation and partly in longitudinal section on the line *f*—*f*, Fig. 7; Fig. 13 is an elevation 55 of the base of the transfer cup; Fig. 14 is a similar view of the receiving portion of the transfer cup holder; Fig. 14^a is a detail view in cross section of a portion of the transfer cup holder; Figs. 15 to 40, inclusive, are 60 views of various parts of the machine, intended to show features of construction or operation not sufficiently illustrated in the preceding views, and Figs. 41 and 42 are longitudinal sectional views in different positions, of a hand-operated transfer cup carrier embodying certain features of my invention; Fig. 43 is a rear view of part of the same in the position shown in Fig. 41; Fig. 44 is a sectional plan view illustrating 65 a modification of one of the features of my invention; Figs. 45 and 46 are, respectively, a plan view and an end view of a supporting arm sometimes employed in connection with the guide or mandrel for the knitted 70 tube, and Fig. 47 is a sectional view illustrating a special construction of a portion 75 of said guide or mandrel which is sometimes resorted to.

Figs. 1, 1^a, 2 and 44 are on the smallest 80 scale, Figs. 3, 4, 5, 7, 8, 10, 11, 12, 13, 14, 23 and 28 to 43 inclusive are on a larger scale, Figs. 6 and 24 to 27 inclusive are on a still larger scale, and Figs. 15 to 22^a inclusive, and Figs. 45, 46 and 47 are on the 85 largest scale.

The fixed frame of the machine is represented at 1, and this frame carries the necessary bearings, supports and guides for the operative members of the machine. 90

The driving shaft of the machine is represented at 2, said shaft being mounted in transverse bearings 3 secured to the depending portions of a segmental frame 4, which is mounted upon the side members of the 95 main frame, as shown in Fig. 6, and said shaft 2 has secured to it as shown in Figs. 3 and 5 a belt pulley 5, a ratchet wheel 6, and a bevel pinion 7, whereby all of the other parts of the machine are driven. Secured to or forming part of the belt pulley 5 is a spur wheel 9, and mounted so as to 100

turn freely on the hub of said belt pulley 5 is a loose pulley 10 bearing such relation to the pulley 5 that the driving belt can be readily shifted from one to the other when it is desired to start or stop the machine.

Secured to the frame 4 is an annular bearing ring 11, and within the latter are mounted three rings 12, 13 and 14, which are free to slide longitudinally in said annular bearing 11 but are incapable of any rotary motion therein, the outermost ring 12 having secured to it a spline 15 which engages with a groove in the bearing 11, as shown in Fig. 6, and said outermost ring being connected to the innermost ring 14 by means of one or more connecting screws 16, each passing through a slot in the intermediate ring 13, as shown in Figs. 3 and 5.

Mounted so as to be free to slide longitudinally and to turn on the annular bearing 11 is a tubular sleeve 19, which is provided with a spline 20, free to turn in a counter-bored portion of a ring 21, and engaging a groove in the face of the hub 22 of a cup 23, the ring 21 being fixedly mounted upon the annular bearing 11 and the hub of the cup 23 being longitudinally confined to the annular portion 24 of a carriage 25 which is adapted to suitable guides 25^a on the side members of the fixed frame 1, as shown in Fig. 7. The annular sleeve 19 terminates at its forward end in a ring 26 of greater diameter than the sleeve and connected thereto by a flaring grid 27, as shown in Figs. 3, 5, 15 and 16. The outer end of each bar of the grid is slotted as shown in Fig. 17 for the reception of the outer portion of a finger 29 whose inner portion projects inwardly beyond the grid bar, these fingers being retained in position radially by engagement of a projecting portion 30 of each finger with a groove in a ring 31, which is secured to the outer face of the ring 26 (see Fig. 15).

The cup 23 has secured to its flanged outer face a slotted ring 32, and each slot of the ring contains a swinging hook 33, which is pivoted to the ring 32 by means of trunnions 34 adapted to a groove in the ring 32, the hooks being retained in place by means of a slotted confining ring 35 secured to the face of the ring 32, as shown in Figs. 18 and 19. The ring 35 is composed of segments independently secured to the ring 32, whereby ready access can be had to any one of a series of hooks 33 by removing the segment of the ring 35 corresponding to said series of hooks, provision being thus afforded for readily removing any broken or defective hook and replacing the same with a perfect one.

Secured to or forming part of the ring 31, is a bracket 36, which is bolted to a slide 37 mounted in guides 37^a on the carriage 25, (as shown in Fig. 7) so as to be free to move

longitudinally on the latter, the removal of 65 the bolt 39, whereby the bracket is secured to the slide 37, permitting rotation of the grid 27 and cup 23 in order to bring to the top a defective hook located in any part of the series, said hooks being more readily accessible when thus brought to the top of the machine than when otherwise located.

The parts 25 and 37 constitute a two-part carriage, and secured to the underside of the slide 37 is a rack 40, which is engaged 75 by a spur wheel 41 on a transverse shaft 42 mounted in suitable bearings on the side members of the fixed frame of the machine, whereby, when said shaft is rotated in one direction or the other, the slide 37 will be 80 moved forwardly or rearwardly, and will, consequently, cause like forward or rearward movement of the sliding sleeve 19, the grid 27 the ring 26, and the parts carried thereby. Certain of the movements of the slide 37 85 are also transmitted to the carriage 25, the latter, however, failing to partake of the movement of the slide when it is beginning either its forward or its rearward travel.

When the slide 37 begins its forward 90 travel from the position shown in Fig. 3 to that shown in Fig. 5 the carriage 25 is locked against forward movement by engagement of a lug 43 on said carriage with a lug 44 on an arm 45 which is pivoted to the fixed 95 frame, as shown in Fig. 12, and has a downwardly projecting pin 46 acted upon by a spring 47 in a hollow stud 49, whereby said pin and the arm 45 have a constant tendency to rise. On the arm 45 is a double-inclined 100 cam block 50, and on the slide 37 is a projecting arm 51 which carries a pair of set screws 52 and 53. After the slide 37 has completed a certain portion of its forward movement the set screw 52 acts upon the 105 rearward inclination of the cam block 50 and depresses the same sufficiently to free the lug 44 from engagement with the lug 43 of the carriage 25, whereupon the latter partakes of the further forward movement of 110 the slide. On the backward movement of the slide and carriage the set screw 53 acts upon the forward inclination of the cam block 50 to depress the arm 45 and carry its lug 44 out of the path of the lug 43 on the 115 carriage, and the rearward movement of said carriage is, therefore, not arrested.

When the carriage 25 and slide 37 are in the retracted position shown in Fig. 3, the points of the hooks 33 engage with the 120 stitches of a "slack course" *x* of the knitted tube which surrounds the central guide or support therefor, this slack course constituting the stitches which are to be transferred to the receiving device, and being usually 125 formed within a short distance of a raised "welt" or rib *y* on the web. (See Figs. 20 and 21.)

Mounted on the annular slide 19 is a ring 54 with a flange or rib 55 around its periphery, and during the early part of the forward movement of the slide 37, independently of the carriage 25, said ribbed periphery of the ring 54 acts upon the rearward faces of the hooks 33 and causes said hooks to swing upon their pivot trunnions to such an extent as to carry their hooked inner ends from a substantially vertical position, as shown in Fig. 3, where they engage with the stitches of the slack course of the normal or contracted tube of knitted web, to substantially a horizontal position, as shown in Fig. 5, in order to stretch or expand the tube to the same diameter as the receiver, the pressure of the ring 54 upon the hooks then causing the hook-carrying cup 23, and with it the carriage 25, to move forwardly with the slide 37 during the further forward movement of the latter, and thereby draw the knitted tube forward over its guide or support. When thus projected, the pointed ends of the hooks register with the quills 56 of a transfer cup 57, or other receiver, which is held in proper relation to the hooks in the manner hereinafter described. When the swinging hooks are projected they stretch a coiled spring 60 surrounding the series of hooks, this spring therefore tending to start the inward swing of the hooks as soon as the pressure of the ring 54 is removed, or relieved, the spring 60 normally resting in a groove formed by recessing the outer portions of the bars of the grid 27, as shown in Figs. 3 and 15. After the hooks 33 have been fully projected and engaged with the quills of the transfer cup, a still further forward movement of the slide 37 takes place, in order that the fingers 29 may strip from the hooks the stitches hanging thereon and apply said stitches to the quills of the transfer cup, and during this transfer movement the hooks are slightly retracted by the pressure of the spring 60, owing to the fact that the ribbed periphery of the ring 54 travels in contact with an inclined shoulder 61 on the back of each hook, as shown in Fig. 11. During this transfer movement, when the forward movement of the carriage 25 is arrested by contact of the hooks 33 with the quills 56, the slide 37 depresses a pin 62 which is free to slide in a box 63 on the carriage 25, as shown in Fig. 5, and is acted upon by a spring 64 tending to project it, consequently the recoil of this spring will force the slide 37 rearwardly, and withdraw the transfer fingers 29 as soon as the forward movement of the shaft 42 ceases. On the backward movement of said shaft 42 the slide 37 moves independently of the carriage 25 until the ring 32 of the hook-carrying cup is engaged by the ring 26 at the end of the sleeve 19, the hooks 33 being thereby

fully retracted, and the further backward movement of the slide 37 imparted to the carriage 25. This movement continues until the parts reach the position from which they originally started, (see Fig. 3) and the points of the hooks enter the stitches of a new slack course which has meantime been adjusted to receive them.

In order to insure the proper relation of the carriage 25 and slide 37 to effect the full expansion of the hooks 33 at the time that they are applying their stitches to the quills of the transfer cup, I employ a registering device which is shown in Figs. 3 and 5, and is as follows: The slide 37 has a beveled notch 65 for engagement with a beveled hook 66 the latter being pivotally mounted upon a stem 67 free to slide in a box 68 on the carriage 25 and normally projected by means of a spring 69 contained in said box 68. When the slide 37 is moving forward independently of the carriage 25 the end of the hook 66 travels on an incline 65a in advance of the notch 65, and, by the time the slide has fully completed its independent movement, the hook has seated itself in the notch 65, and, with the hook in this position, the slide and carriage are in their proper relation to each other to effect the full outward swing or expansion of the hooks 33. If, through any cause, however, the slide and carriage do not occupy this proper relation to one another, the hook 66 will not seat itself in the notch 65, but, before the hooks 33 reach the quills of the transfer cup, the hook 66 will be acted upon by a depressing device, described hereafter, and will be forced down to the bottom of the notch 65, thereby insuring proper adjustment of the slide and carriage in respect to one another.

The guide or support over which the tube of ribbed web is drawn consists of a tube 70 with a forward portion 71 of lesser diameter, said forward portion terminating at its inner end in a plug 72 which is secured to the forward end of the tube 70, as shown in Figs. 3 and 5. Mounted upon the rod 71 is a slide 73 whose inner end is normally maintained in contact with a shoulder on the plug 72 by means of a coiled spring 74 contained in a recess in the slide 73 and bearing against a collar 75 secured to the rod 71 as shown in Figs. 3 and 5.

The slide 73 constitutes a movable member of the web support and its inner end is enlarged in diameter in order to completely fill or slightly expand the knitted tube as it is drawn over the same and said enlarged end of the slide contains a brush 76 which serves as a support for the knitted web when the cutting knife, hereinafter described, is acting upon the same, the inner end of the enlarged portion of the slide

being beveled as shown in Figs. 3 and 5, and being connected by means of screws 77 to a rod 79, guided in the tube 71 and having a slight longitudinal movement imparted to it by the means hereinafter described.

The ring 14 has, at its forward end, bits 94 between which and the beveled face of the slide 73 the knitted web is caused to pass, the bits fitting between the ribs of the outer surface of the web, and bits 94^a (see Fig. 21) on the beveled face of the slide fitting between the ribs of the inner face of the web, in order to guide said ribs into proper registry with the stitch-engaging hooks 33. The forward end of the outer ring 12 is also provided with bits 95, between which the inner ends of the hooks 33 rest when said hooks are in their retracted position, as shown in Fig. 3, there being twice as many of these hooks 33 and bits 95 as there are bits 94, owing to the fact that there is a hook for each wale of the knitted web, both face and back, while there is only one bit 95 for each of the face wales of the web. (See Fig. 22.)

After the proper length of the ribbed web has been drawn forward by the hooks 33, that portion of the web which has been thus drawn forward is severed from the remaining web by cutting mechanism hereinafter described, the slack course stitches at the forward end of the severed web being then applied to the quills of the transfer cup and the carriage 25 being retracted in order that its hooks may engage with the stitches of the next slack course. As, however, it is important to provide for the accurate placing or adjustment of the welt and slack course in order that the cutting knife may act at the proper point between them, and said slack course may register properly with the points of the hooks 33 when the carriage 25 is retracted, forward movement is imparted to the bits 94 and the parts co-operating therewith before the cutting operation and while the carriage 25 is at rest after having completed the first portion of its forward movement. This movement is imparted by means of a cam segment 96 interposed between the outer ring 12 and the annular bearing 11, as shown in Figs. 3, 5, and 10, such segment having a slot 97 (Fig. 23) for the reception of a pin 99 projecting from the ring 12, as shown in Fig. 10, whereby, when said cam segment is moved in one direction the ring 12 and its bits 95 will be moved forward and when the cam segment is moved in the opposite direction said ring 12 and its bits 95 will be drawn rearwardly, corresponding movements being imparted to the ring 14 and its bits 94 by reason of the connection 16 between the two rings which I have before described. At the same time the slide 73

is drawn forward and the front ends of the bits 94, by contact with the welt *y* on the knitted web, are caused to push the same forward to a certain definite position (Fig. 20) in respect to the plane of motion of the subsequently acting cutting knife, the bits 94 and 95 and the slide 73 being then again moved rearward as shown in Fig. 21, in order to permit the cutting knife to act, and also to expose the slack course *x* for the entrance of the hooks 33 when the carriage 25 is again retracted. (See dotted lines Fig. 21.) During this rearward movement the tension on the web between the welt course *y* and the hooks 33 tends to prevent rearward movement of the knitted web, and the retention of the latter is further aided by its contact with the brush 76 which is operated in the manner hereinafter described, and does not follow the bits 94 in their retreating movement.

The bits 94 are slotted and the outer portion of each bit constitutes an elastic tongue having a beveled outer face, as shown in Figs. 20 and 21, and upon such beveled outer face of each of said tongues bears the beveled end of the ring 13 which can be adjusted longitudinally in respect to the rings 12 and 14 by means of an adjusting screw 100, adapted to a threaded opening 95 in the rear end of the ring 13 and having collars 101 and 102 upon opposite sides of a slotted lug 103 at the rear end of the ring 14, as shown in Figs. 3 and 5. By this means the spring fingers of the bits 94, 100 whose forward ends engage and push forward the welts of the successive sections of the web, can be accurately adjusted to accord with the thickness of said web and proper engagement of the successive welts 105 by said spring fingers is thereby insured.

It is advisable also to press the knitted web against the rear faces of the bits 94 before the same passes between said bits and the beveled end of the slide 73, and for this reason I mount upon the guide 70 a tubular slide 104, with annular flange 105 at its forward end, this slide being connected by means of a pin or screw 106 to a rod 107 contained within the tube 70 but having a pin 109 which passes through a slot 110 in said tube and engages an annular groove 111 on the inner face of an adjusting nut 112, the latter being adapted to an externally threaded boss or enlargement on the tube 70, as shown in Fig. 3, whereby, as said nut is turned in one direction or the other, the flange of the slide 104 can be moved toward or from the inner faces of the bits 94 to accord with the thickness of the web which is being acted upon.

As the stitches in a tubular knitted web follow a spiral course, I prefer, in order to secure the desired degree of accuracy in the adjustment of the web, to so dispose the bits 130

94, that their outer ends, which act upon the welt γ to push the web forward, shall present an offset or shoulder 94^a (Fig. 22^a) the ends of the ribs being preferably disposed in a spiral plane, as shown in said figure.

5 In order to cut from the main web, those portions of the same which are drawn out by the successive forward movements of the carriage 25, I employ a rotating knife and operating mechanism therefor as follows, reference being had to Figs. 3, 5, 6, 24, 25, 26 and 27: The spur wheel 9 is connected to the belt pulley 5, and meshes with a spur pinion 115, which, therefore, rotates constantly on 10 the hub of a disk 116, said hub being rotatably mounted on the bearing ring 21, and the disk being provided with a projecting boss 117, in which is mounted, so as to be free to rotate, the trunnion 119 of a swing- 15 ing frame 120, the latter also having a projecting boss 121 containing a longitudinally adjustable sleeve 122, which provides a bearing for the spindle 123 of the constantly rotating cutting knife 124, the knife spindle 20 having secured to it a spur pinion 125, and the latter meshing with a spur wheel 126 secured to a spindle 127, which is free to turn in the trunnion 119 and is provided at its rear end with a spur pinion 129, mesh- 25 ing with the pinion 115.

Secured to or forming part of the disk 116 is a spur wheel 130 which is in mesh with a spur pinion 131 secured to the hub of the disk 132, the latter being free to turn 30 on the driving shaft 2 but carrying a pawl 133 adapted to engage with the teeth of the ratchet wheel 6 on said driving shaft. When, therefore, the pawl 133 is in engagement with the teeth of the ratchet wheel 6, the disk 116 35 will be rotated and the cutting knife will be carried in a circular path around the axis of the machine, and, if said knife has been previously depressed so as to act upon the web which has been drawn forwardly over 40 the brush 76 it will cut the forward portion of said web from the remaining portion or body of the web.

The pawl 133 is normally moved to engage the teeth of the ratchet wheel 6, by 45 means of a spring 134, but at all times except when a cutting operation is to be performed, said pawl is held free from engagement with the teeth of the ratchet wheel by contact of the tail of the pawl with a trip- 50 per arm 135, which is pivotally mounted be- 55 tween lugs 136 on the face of the disk 116 but can be swung outward from the face of said disk by a cam 137 on a bar 139, the latter being transversely guided on the fixed 60 frame of the machine and operated in the manner hereinafter described. When the tripper 135 is thus swung outward the spring 134 causes the pawl 133 to engage the 65 teeth of the ratchet wheel 6 and rotating motion is therefore imparted to the disk 116,

the parts being shown in this relation to each other in Fig. 6.

The number of teeth in the pinion 131 is so proportioned in respect to the number of teeth in the spur wheel 130 that the pinion 70 131 will make a certain number of complete revolutions for each single revolution of the spur wheel 130. During the time that the tripper 135 is being carried around by the spur wheel 130 the bar 139 has been restored 75 to its original position, shown in Fig. 24, and the tripper 135 has resumed its normal position, consequently, when the wheel 130 has made a complete revolution the lower end of the tripper 135 will act upon the tail 80 of the pawl 133 and will again lift said pawl from engagement with the teeth of the ratchet wheel 6, thereby stopping the rotation of the wheel 130 and the parts carried thereby.

By so proportioning the number of teeth in the pinion 131 and spur wheel 130, that two or more revolutions of the latter will be required before the tripper 135 contacts with the tail of the pawl 133, two or more 85 revolutions of the knife 124, around the tube of knitted web will be permitted, the bar 139, in that case, not being restored to its retracted position, until the spur wheel 130 is making its last revolution.

90 In order to prevent sudden strain upon and jarring of the parts when the pawl 133 is suddenly moved into engagement with the rapidly moving ratchet wheel 6, said pawl is not hung directly to the disk 132 95 but to a ring 310 rotatably mounted on said disk, as shown in Fig. 27, a spring 311 being interposed between an internal shoulder 312 in the ring and an external shoulder 313 on the hub of the disk as shown in Fig. 26, 100 whereby the movement of the ring is transmitted to the disk through the medium of the spring and any sudden shock upon the driven parts is avoided.

At all times, except during the cutting 110 operation, the rotary knife 124 occupies the position shown in Fig. 3, but when it is desired to swing the knife down into cutting relation with the fabric resting upon the brush 76 as shown in Fig. 5 a spur pinion 140 on the trunnion 119 is actuated by means of a toothed segment 141 on a disk 142, whose hub is rotatably mounted upon the hub of the disk 116, as shown in Figs. 3, 5 and 6. The disk 142 is normally re- 115 tained in such relation to the spur pinion 140 as to maintain the cutting knife 124 in the position shown in Fig. 3, this result being effected by means of a coiled spring 143 contained in a recess 144 in the hub of the 120 disk 142 and bearing against a lug 145 which projects into said recess from the hub of the disk 116, as shown in Fig. 6.

Hung between suitable lugs on the face of the disk 142 is a trigger 146, which is 125 130

normally pressed into contact with the face of a segmental flange 147 on the spur wheel 130 by means of a spring 149 contained in a recess in the disk 142, as shown in Fig. 5, and the first result of the movement of the bar 139 is to cause a lug 150 on said bar (see Fig. 25) to engage the outer end of the trigger 146 and move the same, and with it the disk 142, in the direction of the arrow shown in Fig. 6, the result, owing to the engagement of the segment 141 and pinion 140, being to swing the trunnion 119 of the knife-mounting frame 120 in its bearing 117 to such an extent as to carry the knife from the outer position shown in Fig. 3 to the inner position shown in Fig. 5, the trigger 146 then snapping into a notch 151 in the flange 147 so as to lock the disk 142 and spur wheel 130 together and cause them both to rotate in unison, as soon as the pawl 133 has, by the outward movement of the trigger 135, been permitted to engage with the teeth of the ratchet wheel 6. The segmental flange 147 is adjustable circumferentially on the spur wheel 130, as shown in Fig. 6, in order to determine the extent of the downward swing of the knife mounting 120, and the depth of cut of the knife 124, the swing of the knife being decreased as the flange 147 is moved to bring its notch 151 toward the position of rest of the trigger 146, and increased as said flange is moved to carry its notch 151 away from such position of rest.

As soon as the spur wheel 130 and disk 116 have completed a full revolution the trigger 146 will be forced out of engagement with the notch 151 in the flange 147 by the action of a cam 152 on the bar 139 (see Fig. 25) the latter having meantime been moved to its rearward position, as shown in Fig. 24, so as to bring said cam into position for acting upon the trigger 146 when a full revolution of the disk 116 has been effected. As soon as the trigger 146 clears the notch 151 the spring 143 acts upon the hub of the disk 142 to restore the same to its normal position, thereby causing the segment 141 to partially rotate the pinion 140 and raise the knife from its cutting position, (shown in Fig. 5) to its inactive position (shown in Fig. 3), the trigger 146 then contacting with the lug 150 on the bar 139 preparatory to the next cutting operation. The knife, being rotated constantly by means of the gear wheels 9, 115 and 129, is shielded in all of its various positions by means of a segmental hood 153, secured to the member 4 of the fixed frame of the machine.

The longitudinal position of the knife 124 can be varied, as desired, by longitudinal adjustment of the sleeve 122 in the boss 121 of the swinging knife-mounting frame 120, the pinion 125 being longer than the

face of the spur wheel 126, in order to permit of such adjustment, which may be rendered necessary by the fact that in some webs the slack course may be farther from the welt course than in other webs.

In order to provide for feeding the tubular web forward on the guide 70, and preventing the drag upon the hooks 33 which would result if the forward feed of the fabric was due entirely to the pull of said hooks thereon when the carriage 25 moved forward, I provide an independent feeding means (see Figs. 1^a and 28 to 31) comprising a pair of clamping jaws constituting parts of levers 154 pivotally mounted upon a slide 155, the latter being mounted to move longitudinally upon a bar 156 located midway between the side members of the main frame at a point in the rear of the segmental frame member 4. (See Figs. 28 to 31 inclusive.) The levers are normally held, by means of a spring 157, in such position that their jaws are free from contact with the tubular web on the guide 70, as shown in Fig. 28, but said levers may be operated so as to cause their jaws to engage the tubular web, as shown in Fig. 29, when the depending arms of the levers are acted upon by a wedge 159 secured to or forming part of a slide 160, which is mounted on the top of the bar 156 and is provided also with lugs 161. (See Figs. 30 and 31.) The slide 160 is connected by means of an arm 162 to a sliding bar 163, the latter being mounted upon the top of one of the side members of the fixed frame, and being moved at the proper times by the carriage 25 through the medium of any desired connection between the two, as, for instance, by means of a projection 164 on the carriage entering an opening in an arm 165 projecting from the slide 163, as shown in Fig. 32.

When the carriage 25 is retracted, as shown in Fig. 3, the wedge 159 and lugs 161 occupy the relation to the lever arms 154 shown in Fig. 30, but as soon as the carriage 25 begins to move forwardly the wedge 159 acts to separate the lower arms of the levers and thereby cause their jaws to engage the web on the guide 70, (see Figs. 29 and 31). As soon as this has been effected the slide 160 causes the bearing 155 to move forward with it, carrying the levers 154 and causing their jaws to pull the tubular web forward over the guide 70 at the same rate of speed as the travel of the carriage 25. As soon as said carriage begins its backward movement the wedge 159 is withdrawn from between the lever arms 154, the spring 157 acts upon said arms so as to open the jaws of the same and release the tubular web, and the lugs 161 contact with the lower arms of the levers to cause the same, together with the bearing 155, to move backward with the slide 160, these

operations being repeated on each reciprocating movement of the carriage 25.

In order to delay the movement of the bearing 155, until the movement of the cam slide 160 in either direction has first been effected, said bearing 155 has a friction plate 315 in contact with the edge of the guide bar 156, the pressure of this plate being regulated by an adjusting screw 316.

The transfer cups 57 are automatically adjusted to and held in position for the reception of the stitches from the hooks 33 by means of a rotating turret having a plurality of equidistantly disposed cup holders 166, four of which are shown in the present instance, these cup holders being connected by arms 167 to a hub 169 which is mounted so as to be free to turn upon a pivot pin 170 depending from a head 171 secured to or constituting part of a yoke 172, the latter being mounted upon the fixed frame 1 of the machine, as shown in Fig. 8, and vertical adjustment of the pivot pin 170 being permitted by reason of the fact that it has a screw stem 173 passing through an opening in the top of the head 171 and provided with a nut 174 resting on said head, as shown in Fig. 4, a locking screw 175 serving to secure the pivot pin in position after any vertical adjustment of the same. At its lower end the pivot pin 170 has an enlarged and detachable head 176, which serves to support a spur wheel 177, mounted so as to turn loosely on the head, but carrying a spring-pressed pawl 179 which engages with the teeth of a ratchet wheel 190 secured to the hub 169 of the turret, as shown in Figs. 4 and 33.

In addition to its duty of supporting the turret, the bolt head 176 serves, when the carriage 25 is approaching the forward limit of its movement, to bear upon the inclined top of the hook 66, and thus force the same down into the notch 65 on the slide 37 and bring said slide and the carriage 25 into proper relation to each other.

Meshing with the spur wheel 177 is a rack 191, secured to or forming part of a bar 192, which is mounted upon one of the side members of the frame 1 of the machine so as to be free to slide longitudinally thereon. (See Figs. 34 and 35.) The rack bar 192 has two lugs 193 and 194, the lug 193 being secured to the bar but the lug 194 being carried by a pivoted arm 317, which has a pin 319 adapted to be acted upon by a cam plate 320 on the frame 1, as shown in Fig. 35.

Projecting from the carriage 25 is a lug 321 and on the forward movement of the carriage this lug engages with the lug 193 of the rack bar and pushes the latter forward so as to turn the spur wheel 177, this movement, however, having no effect upon the turret, the pawl 179 slipping over the teeth of the ratchet wheel 190 during such

movement. When the carriage begins to move backward its lug 321 engages with the lug 194 carried by the pivoted arm 317 on the rack bar and the first portion of the backward movement of the carriage is transmitted to the rack bar and by the latter to the spur wheel 177 and to the turret until the latter has been moved to the extent of one-quarter of a turn, there being, however, so much lost motion of the lug 321 between the lugs 193 and 194 that the transfer hooks 33 and the parts coöperating therewith will have been moved so far away from the transfer cup to whose quills the stitches of the knitted web have just been applied, that said hooks and their appurtenances will offer no obstacle to the turning movement of the turret. The joint movement of the carriage 25 and the rack bar 192 continues until the pin 319 on the arm 317 is acted upon by the cam plate 320, whereupon said arm 317 will be lifted to such an extent as to carry its lug 194 free from contact with the lug 321 on the carriage, and the movement of the rack bar will be arrested, the carriage 25 continuing its further rearward movement.

Each of the transfer cup holders 166 of the turret has a projecting stem 195 notched at the end, as shown in Fig. 4, for engagement with a correspondingly notched portion of the outer end of the tube 71, whereby, when a transfer cup is moved into position to receive the stitches from the transfer hooks 33, the cup holder and the tube 71 will be locked in position longitudinally, and the end of said tube 71 will be supported vertically by the stem 195. Each of the stems 195 is tubular for the reception of a rod 350 which is notched at its outer end for engagement with the notched end of the rod 79 contained in the tube 71. The lower portion of the pivot pin 170 is reduced in diameter and each rod 350 projects into the interior of the hub of the turret and has a head 351 for engagement with the upper end of a lever 352, pivotally mounted upon the reduced portion of the pivot pin, the lower end of said lever passing through a slot or recess in the head 176 of the pivot pin, and being actuated as described hereafter, so as to draw forward the rod 79, and the slide 73 connected thereto.

Each of the cup holders 166 has mounted upon it a ring 196 with latches 197 for engaging a flange 199 on the transfer cup and holding the same in place on the cup holder, the flange 199 having notches 200 for the reception of these locking latches 197, as shown in Fig. 13. The ring 196 is acted upon by a spring 201 (Fig. 14) tending to retain the latches 197 in locking position, but each of the latches has a beveled edge 202 (Fig. 14^a) for contact with the side wall of its respective notch in the flange 199 of the transfer cup when the latter is being

- applied to the holder, the latch being thereby forced backward against the action of the spring 201, but snapping into position under the action of the spring as soon as it has passed through the notch in the flange 199 of the cup.
- In order to effect the automatic release of the transfer cup from the cup holder when said cup has been carried to the discharging position, a bent arm 203 on the ring 196 comes into contact with a lug 356 projecting from the turret-carrying yoke 172 as shown in Fig. 8, and causes backward movement of the ring 196 against the action of the spring 201 to an extent sufficient to draw the catches 197 into line with the notches 200 in the flange 199 of the transfer cup, the removal of the latter from the cup holder being thereby permitted. This removal is effected by means of cams 205 (Fig. 8) on a ring 206 rotatably mounted on the cup holder 166 and normally held by means of a spring 207 (Fig. 14) in such position as to enter corresponding recesses 209 (Fig. 13) in the transfer cup when the latter is applied to the holder, the arm having a projection 210, which, as the holder approaches the position for the discharge of the transfer cup therefrom, and just after the ring 196 has been operated to release the cup from the catches 197, strikes the lug 356 and thereby turns the ring 206 against the action of its spring 207 and causes the cams 205 to eject the transfer cup from the holder, the ejected cup then sliding down an inclined rib 211 on the cup holder as shown in Fig. 8 and being delivered into a suitable receptacle or onto a suitable carrier, whereby it may be conveyed to any desired point.
- In order to prevent the momentum of the turret from causing it to overrun its quarter turn, I provide, in the top of each of the turret arms 167, a concave or beveled socket for the reception of the convex or beveled lower end of a spring-pressed bolt 330 guided in a boss 331 on the head 171 of the turret-carrying yoke 172 as shown in Fig. 4, the engagement of the bolt and socket serving to arrest the movement of the turret as soon as a quarter turn of the latter has been effected, and thus insuring the presentation of the transfer cups in proper registry with the transfer hooks 33, and also the proper presentation of an empty cup holder to a magazine hereinafter described. The bolt 330 will be forced back out of engagement with the socket in the turret arm, whenever power is applied to the turret to turn the same.
- The successive transfer cups are fed to the rotating turret in the following manner: Secured to one end of the fixed frame 1 of the machine is a tubular guide 215, in which is mounted, so as to slide longitudinally, a horizontal cylindrical magazine 216,

having, at its rear end, a flange 217 which limits its movement toward the turret. The magazine 216 is provided with internal longitudinal grooves 219 for the reception of projecting lugs 220 on the transfer cups, whereby said transfer cups will be held in the magazine in proper position for application to the cup holders on the turret. (See Fig. 9.) A plunger 221 is guided in the magazine 216 and acts upon the outermost transfer cup therein to force the entire series of transfer cups inwardly through the magazine, movement being imparted to the plunger by means of a weight 222 which is connected by a cord or chain 223, passing around a sheave 224, to the outer end of a stem 225, the latter being secured to the plunger 221 and passing through a guide 226 suitably located beyond the end of the tubular guide 215. The foremost transfer cup in the magazine is retained in position therein by means of spring bolts 227 guided in bosses 229 at the inner end of the magazine, these spring bolts being forced outward by means of a flange 325 on the ring 206 when the transfer cup holder is adjusted in proper relation to the magazine to receive the transfer cup therefrom. Upon the forward movement of the carriage 25 a bar 229^a is caused to move with it, and this bar is provided with lugs 230 and 231 for acting upon the lower boss 229 on the magazine and moving the latter from and toward the transfer cup holder of the turret, it being understood that the frictional hold of the tube 215 upon the magazine is sufficient to prevent any movement of the same, due to the action of the plunger 221, or any movement not caused by contact of one or other of the lugs 230 and 231 with the boss 229. The lug 230 is adjustable longitudinally on the bar 229^a, as shown in Fig. 4, and it is so set that it strikes the boss 229 at such a stage of the forward movement of the carriage 25 that by the time said carriage has completed its forward movement the magazine will have been pushed back so far that when the turret swings on the retraction of the carriage 25, the magazine will clear the projecting stem 195 of the transfer cup-holder 166 to which a transfer cup has been applied. (See Fig. 36.)

The first portion of the backward movement of the carriage 25 is devoted, among other things, to imparting movement to the extent of a quarter turn, to the turret so as to carry away from the magazine 216 the cup-holder to which the transfer cup has just been applied and to bring into operative relation to said magazine the cup-holder from which the transfer cup with the knitted web applied thereto, has just been discharged. As the rearward movement of the carriage 25 continues, the outermost lug 231 on the bar 229^a comes into con-

tact with the boss 229 on the magazine, and pulls the same forwardly in the supporting tube 215, this movement continuing until the foremost transfer cup in the magazine has been applied to the empty holder 166 on the turret. On the outward movement of the magazine the spring bolts 227 are projected to engaging position as soon as they pass inwardly beyond the lugs 220 of the foremost transfer cup, and are then in position to engage the lugs 220 of the next transfer cup of the series as the backward movement of the magazine continues. (See Fig. 36.)

15 The base of each transfer cup is recessed as shown at 326 in order that it will not contact with the points of the quills of the preceding cup in the magazine, as shown in Fig. 4, as such contact might injure the delicate points of said quills.

20 The rotation of the shaft 42, the actuation of the cutting mechanism, and the reciprocating movements of the rings 12 and 14 and slide 73 are effected at the proper times by means of operating devices mounted upon an endless chain 235 which engages a driving sprocket wheel 236 and a supporting and guiding sprocket wheel 237 the latter being rotatably mounted on a longitudinally adjustable stud on one of the side members of the fixed frame, and the sprocket wheel 236 being secured to a shaft 240 which has a bevel wheel 241 meshing with the bevel wheel 7 on the driving shaft 2, as shown in Fig. 1. The chain 235 carries a cam 242 for acting upon and lifting the outer end of an arm 243 connected to the cam segment 96, as shown in Fig. 10 and the arm being restored to its normal position by the action

30 of a spring 244. To prevent sagging of the chain at the point where the cam 242 acts upon the arm 243, a fixed support 245 for the upper run of the chain is secured to the side frame of the machine and projects below said upper run of the chain, as shown in Fig. 1.

35 The bar 139 which throws the cutting mechanism out of action is normally retained in its inner position by means of a spring 246 interposed between the fixed frame of the machine and a pin 247 on said bar, as shown in Fig. 24, and the outward movement of the bar is effected by means of a lug 249 on the chain 235, said lug acting upon an arm 251 on a rock shaft 252 which is mounted in a suitable bearing on one of the side members of the fixed frame, as shown in Figs. 1 and 25, and carries a toothed sector 251^a which meshes with a rack 251^b on the side of the bar 139.

40 The shaft 42 has, at its outer end, a spur wheel 253, which is in mesh with a rack 254 on a sliding frame or yoke 255, whereby said shaft 42 is driven and to the said yoke is pivoted a lever 256 which has two

45 arms 257 and 259, the arm 257 being provided with an antifriction roller which travels on a cam plate 260 secured to the side member of the fixed frame, and the arm 259 being adapted to contact with lugs 261 and 262 on the chain 235. (See Figs. 1, 2, 7, 37, 38 and 39.) When the lug 261 acts upon the lever arm 259 the roller on the arm 257 is traveling upon the flat top of the cam bar 260, as shown in Fig. 37. The 50 said cam bar has two depressions 263 and 264, with inclined connections between the same and between the depression 263 and the flat top of the bar.

55 As the frame 255, and its lever 256, is carried forward by contact of the lug 261 with the arm 259 the roller on the arm 257 reaches the first depression 263 and the pressure of the lug on the arm 259 causes the roller to drop into said depression, as shown in Fig. 38, thereby removing the arm 259 from contact with the lug 261 and temporarily arresting the forward movement of the frame 255 until the second projection 262 on the pattern chain 235 comes into contact with said arm 259 and imparts further forward movement to the same and to the frame 255 until the roller on the arm 257 reaches the second depression 264 of the cam bar, whereupon it drops into said 60 depression 264 and removes the arm 259 from engagement with the lug 262 as shown in Fig. 39, thus completing the forward movement of the carriage, and insuring the necessary dwell in the forward movement 65 while the cutting mechanism is severing from the main portion of the knitted tube that portion of the same which has been drawn out by the first portion of the movement.

70 The retraction of the frame 255 is effected in a manner similar to its forward movement, but such retracting movement is continuous from start to finish, a lug 265 on the chain 235 engaging with a lever 266 on the lower member of the frame 255, said lever 266 having arms 267 and 269 the former having a roller for riding on a cam bar 270 which has a single depression 271, and the arm 269 engaging with the lug 265 75 on the pattern chain, as shown in Fig. 40.

75 The levers 256 and 266 constitute triggers whereby the frame 255 can be placed under the control of the chain 235 or released from such control.

80 The lower end of the lever 252 in the pivot pin of the turret, engages with the inner arm of a lever 354 hung to a bearing on the side member of the frame 1 (see Fig. 8) the outer arm of said lever being engaged at the proper time by a lug 355 on the chain (Fig. 1) to cause movement of the lever 252 which will effect inward movement of the rod 350 engaged therewith, a spring 357, contained in the tubular stud 195, moving the 85

parts in the opposite direction. By this means the rod 79, which engages the rod 350 and is connected to the brush-carrying sleeve 73, is operated at the proper time to pull 5 said sleeve forward and released to permit said sleeve to be moved back again under the action of the spring 74.

- The machine as described is designed to be automatic in its operation, requiring only 10 that the magazine 216 shall be kept properly supplied with transfer cups, but many of the novel features of my invention may be embodied in machines which are not automatic in their operation but in which some 15 or all of the necessary manipulations are performed by hand, for instance, the rotative movements may be imparted to the shaft 42 by means of a suitable hand crank and the movements of the bar 139 for controlling the operation of the cutting mechanism may also be imparted thereto by hand, as may also the movements of the arm 243 of the cam segment 96, or the web-adjusting movements of the rings 12 and 14 may be 20 effected by pressure of the hand imparted directly thereto, and the web may be drawn forward over the guide 70 by hand instead of by means of the automatic feeding device which I have described, and instead of feeding 25 the transfer cups to the turret automatically they may be applied thereto and removed therefrom by hand, or the turret may be dispensed with altogether, and a transfer cup holder movable from and 30 toward the stitch-engaging and expanding devices may be used, or a swinging holder may be employed for the purpose of receiving the transfer cups in succession and presenting them in position to receive 35 the stitches from the transfer hooks, such a device being shown in Figs. 41, 42 and 43, and comprising an annular holder 275 mounted on studs 276 carried by a bracket frame 277 on the fixed frame 1, the holder 40 being adjustable on said studs either to the horizontal position shown in Fig. 41, or to the vertical position shown in Fig. 42, an adjustable stop 279 contacting with the annular holder 275 to determine its horizontal 45 position and a stop pin 290 contacting with a shoulder 291 on the holder to determine its vertical position.
- Mounted on the annular holder is a ring 50 carrying locking bolts 293, said ring 55 having jaws 294 which embrace a cam 295 on one of the studs 276 whereby, as the holder is swung from one position to the other, a partial turning movement will be imparted to the ring 292.
- 60 When the holder is in the vertical position shown in Fig. 42 the bolts 293 are in position to pass through the notches in the flange 199 of the transfer cup, these notches being caused to register with the bolts by 65 engagement of a fixed stud 296 on the holder

with another notch in the flange but as the holder, with the transfer cup therein, is turned from the vertical to the horizontal position the turning movement of the ring 292 will cause its bolts to be carried in front of the flange and thereby securely lock the latter to the holder, the cup being unlocked from the holder as the latter is turned from the horizontal to the vertical position again. 70

The holder 275 has a projecting stem 300 with a key 301 for engagement with a slot in the forward end of the tube 71, so as to lock the holder and tube together against any longitudinal movement of one in respect to the other, a sliding sleeve 297 on the stem 300, being projected by means of a spring 299, and carrying a bolt 302 for entering an opening in the end of the web guide 71, in order to provide vertical support for the latter. 75

Instead of employing interlocking stems 80 on the web support and on the carrier for the stitch-receiver, or in addition thereto, I, in some cases, swell the rear end of the web support as shown at 375 in Fig. 1^a and 85 adapt this portion of the same to a correspondingly recessed retainer 376, the web passing between the retainer and the enlarged portion of the web support so as to 90 prevent longitudinal movement of the latter in either direction. 95

The exterior of the enlargement 375 and the interior of the retainer 376 are, by preference, bitted for engagement with the ribs of the knitted web and thus constitute the 100 initial guide for said web.

Instead of causing the chain 235 to exert the amount of force necessary to rotate the shaft 42, it may simply serve to govern the application of power to said shaft, one 105 instance of such construction being shown in Fig. 44 in which 335 represents a power shaft having a bevel wheel 336, which meshes with bevel wheels 337 and 339, loose on the shaft 42, the wheel 337 rotating 110 in one direction and the wheel 339 in the opposite direction. Splined on the shaft 42 between the bevel wheels 337 and 339 is a clutch sleeve 340 which is adapted to engage with either a right-hand clutch member on one bevel wheel or with a left-hand clutch member on the other or to occupy a 115 position between the wheels, when no movement of the shaft 42 is desired. This clutch sleeve is controlled by a lever 341 hung to the fixed frame and acted upon by a spring 342 which tends to throw the clutch sleeve into engagement with the clutch member on one of the bevel wheels 337 or 339. By means of suitable lugs or cam-plates 343 on the chain 235 this lever can be so controlled 120 to effect either forward or backward movement of the shaft 42 or a cessation of movement of the same. 125

If it becomes necessary to provide verti- 130

cal support, or both vertical and lateral support, for the projecting end of the tube 71, in order to insure the proper position of the same when the interlocking stem 195 of the 5 turret is swinging into locking relation with it, such support may be provided by means of a laterally sliding bar 360 shown in Figs. 45 and 46, this bar having a concave recess at its inner end and being adapted to engage the tube 71 at a point where an external annular groove 361 is formed there-in immediately back of the locking portion 10 at the end of the tube. This bar will be projected to engage the tube 71 as soon as the 15 stitch-receiver on the swinging turret has drawn the knitted web clear of the same and before the stem 195 of the advancing stitch-receiver engages with the interlocking head of the tube.

20 To and fro movement may be imparted to the rod 360 by means similar to those employed for imparting like movement to the bar 139 which controls the movements of the cutting knife, it being preferable however to 25 retract the tube by means of the spring and to advance it by the action of the cam on the chain 235.

In some cases I prefer to so shape the brush or the web support adjacent thereto that it will present opposite to the inclined points of the hooks 33 a face substantially at right angles to said points of the hooks as shown in Fig. 47, this conformation of the web support having the effect of increasing the certainty of the engagement of each hook with its corresponding stitch of the slack course of the web, since it holds the said slack course close up to the points of the hooks, and insures the passage of the latter through the stitches, and also into and through a portion of the web support as well, the latter being slotted or grooved for the passage of the hooks, if any portion of said right angled faces of the support is contained in a metallic element of the same.

Instead of, or in addition to, the formation of the pusher bits 94 so that their ends will present an offset or spiral plane, the grooves or slots between the bits 95 may be of varying depth, whereby, when the retracted hooks 33 seat against the bases of said grooves, their points will accord with the offset or spirally disposed stitches of the "slack course" which said hooks engage.

55 Many other modifications of the various
elements of the machine which I have de-
vised, and which contribute to the successful
operation of said machine, will suggest
themselves to those familiar with the art to
60 which said machine appertains, and I have
not considered it necessary to encumber my
specification with detailed descriptions of
such modifications but have couched many
of my claims in broad terms with the pur-
65 pose of bringing within their scope not only

the constructions which I have selected for illustrating my invention but modified or equivalent constructions capable of performing similar functions.

The machine may be used for running-on plain webs as well as ribbed webs, and the machine may, without change of its fundamental characteristics, be adapted for transferring flat webs as well as tubular webs, and a knitting machine cylinder and its needles may, if desired, replace the transfer cup and its quills, the needles receiving the stitches directly from the transfer hooks, hence this element of the machine I have in many of the claims referred to as a "receiver." 70 75 80

I have not represented the knitted web in any figures of the drawing except Figs. 20, 21 and 47, as such representation in the other figures would not conduce to a better understanding of the operation of the machine but would rather tend to obscure a proper showing of the construction of the parts. 85

I claim:—

1. In a machine for running-on knitted web, the combination, in operative relation to one another, of means for receiving the stitches of the web, and means for engaging said stitches and transferring them to said receiver. 95

2. In a machine for running-on knitted web, the combination, in operative relation to one another, of means for receiving the stitches of the knitted web, and means for engaging said stitches, stretching or expanding the web, and then applying the stitches to the receiver. 100

3. In a machine for running-on knitted web, the combination, in operative relation to one another, of means for receiving the stitches of the knitted web, and means for engaging the stitches of the web, drawing the web forward and applying the stitches to the receiving means. 105 110

4. In a machine for running-on knitted web, the combination, in operative relation to one another, of means for receiving the stitches of the knitted web, with means for engaging the stitches, stretching or expanding the web, drawing the same forward and applying the stitches to the receiving means.

5. In a machine for running-on knitted web, the combination, in operative relation 12 to one another, of means for receiving the stitches, means for engaging said stitches and transferring them to the receiving means, and means for moving the latter into and out of operative relation to said transferring means. 12

6. In a machine for running-on knitted web, the combination, in operative relation to one another, of means for receiving the stitches, means for engaging said stitches, 15

drawing the web forward, and transferring the stitches to the receiving means, and means for moving the latter into and out of operative relation to said transferring means.

7. In a machine for running-on knitted web, the combination, in operative relation to one another, of means for receiving the stitches, means for engaging said stitches, 10 expanding the web, drawing said web forward, and transferring the stitches to the receiving means, and means for moving the latter into and out of operative relation to said transferring means.

15 8. A machine for running-on knitted web having means for engaging the stitches to be transferred and drawing the web forward through the medium of such engaging means.

20 9. A machine for running-on knitted web having means for engaging the stitches to be transferred, expanding the web, and drawing the same forward through the medium of said engaging means.

25 10. A machine for running on knitted web having means for engaging the stitches to be transferred and drawing the web forward through the medium of such engaging means, and means for severing the portion

30 of the web thus drawn forward from the remaining portion.

35 11. A machine for running-on ribbed knitted web, having means for engaging the stitches to be transferred and drawing the web forward through the medium of such engaging means and means for engaging with the ribs of the web for guiding the same during such forward movement.

40 12. In a machine for running-on knitted web, the combination, in operative relation to one another, of means for receiving the stitches to be transferred, means for engaging said stitches and after such engagement drawing the web forwardly and transfer-

45 ring the stitches to the receiving means, and cutting devices for severing the drawn-out portion of the web from the remaining portion.

50 13. In a machine for running-on knitted web, the combination in operative relation to one another, of means for receiving the stitches to be transferred, means for engaging the said stitches and after such engagement stretching the web, drawing the same forwardly, and transferring the stitches to the receiving means, and cutting devices for severing the drawn-out portion of the web from the remaining portion.

55 14. A machine for running-on knitted web, having means for engaging the stitches to be transferred while the same are in the plane of the normal cylindrical surface of the web, and then expanding the web to bring the stitches into a plane substantially

at right angles to that originally occupied 65 by them.

15. In a machine for running-on knitted web, the combination, in operative relation to one another, of means for receiving the stitches to be transferred, means for engaging said stitches and expanding the web to bring the stitches into a plane substantially at right angles to their position in the un-expanded web, and means for transferring the stitches to the receiving means. 75

16. In a machine for running-on knitted web, the combination, in operative relation to one another, of a receiver having members for receiving the stitches to be transferred, means for simultaneously engaging 80 the entire series of stitches to be transferred and adjusting them into position for transfer to the receiving members, and means for simultaneously removing the entire series of stitches from the transfer members to the 85 receiving members.

17. In a machine for running-on knitted web, the combination of swinging hooks for engaging the stitches to be transferred, a carrier for said hooks, and means for moving 90 said carrier in a direction parallel with the web.

18. In a machine for running-on knitted web, the combination of swinging hooks for engaging the stitches to be transferred, 95 a carrier for said hooks, means for moving said carrier in a direction parallel with the web, a receiver for the stitches, and means for transferring the stitches from the hooks to said receiver.

19. In a machine for running-on knitted web, the combination of swinging hooks for engaging the stitches to be transferred, a carrier for said hooks, means for moving 100 said carrier in a direction parallel with the web, an expander for the hooks, and means for moving said expander independently of the hook carrier.

20. In a machine for running-on knitted web, the combination of swinging hooks for 110 engaging the stitches to be transferred, a carrier for said hooks, means for moving said carrier in a direction parallel with the web, an expander for the hooks, means for moving said expander independently of the 115 hook carrier, a receiver for the stitches, and means for transferring the stitches from the hooks to said receiver.

21. In a machine for running-on knitted web, the combination of swinging hooks for 120 engaging the stitches to be transferred, a carrier for said hooks, means for moving said carrier in a direction parallel with the web, an expander for the hooks, and means for moving said expander independently of 125 the hook carrier, said expander being combined with a grid for guiding the hooks in their swinging movement.

22. In a machine for running-on knitted web, the combination of swinging hooks for engaging the stitches to be transferred, a receiver for the stitches, a carrier for said hooks, means for moving said carrier in a direction parallel with the web, an expander for the hooks, and means for moving said expander independently of the hook carrier, said expander being combined with a grid 5 for guiding the hooks in their swinging movement and with fingers for pushing the stitches from the hooks onto the receiver.
23. In a machine for running-on knitted web, the combination of a receiver for the transferred stitches, means for engaging the stitches to be transferred and applying them to the members of the receiver, means for conveying the stitches from the transferring to the receiving means, and means for 10 slightly retracting such engaging devices during the transfer operation.
24. In a machine for running-on knitted web, the combination of a series of hooks for engaging the stitches to be transferred, a carrier for said hooks, an expander acting upon the hooks to spread the web after the stitches have been engaged by the hooks, and a spring for acting upon the hooks when they are thus expanded.
25. In a machine for running-on knitted web, the combination of means for engaging the stitches, means for imparting a two-stage forward movement thereto, and a web cutter operating between the stages of the movement.
26. In a machine for running-on knitted web, the combination of means for engaging and expanding the stitches, means for imparting a two-stage forward movement thereto, and a web cutter operating between the stages of the movement.
27. In a machine for running-on knitted web, the combination of a receiver for the stitches to be transferred, a transferring device provided with means for engaging the stitches and delivering them to the receiver, a web cutter, and means for imparting a two-stage movement to the transfer devices, one portion of said movement preceding the cutting operation and the other portion following it.
28. In a machine for running-on knitted web, the combination of a receiver for the transferred stitches, means for engaging the 55 stitches to be transferred, and expanding them prior to their application to the receiver, and means for insuring a full expansion of said engaging devices on their approach to the receiver.
29. In a machine for running-on knitted web, the combination of a series of swinging hooks for engaging the stitches to be transferred, a carrier to which said hooks are pivoted, and a grid in advance of said car-
- rier for guiding the hooks in their swinging movement, said grid and carrier being rotatably mounted.
30. In a machine for running-on knitted web, the combination of a series of swinging hooks for engaging the stitches to be transferred, a carrier upon which said hooks are pivotally mounted, and an expander for the hooks having a grid for guiding said hooks during their swinging movement, said expander and hook-carrier being rotatably mounted.
31. In a machine for running-on knitted web, the combination of a series of swinging hooks for engaging the stitches to be transferred, a carrier upon which said hooks are pivotally mounted, an expander for the hooks having a grid for guiding said hooks during their swinging movement, said expander and hook-carrier being rotatably mounted, and means for normally securing them against rotation.
32. In a machine for running-on knitted web, the combination of a series of hooks for engaging the stitches to be transferred, a carrier upon which said hooks are pivotally mounted, and a grid for guiding the hooks during their swinging movement, said grid having fingers for discharging the stitches from the hooks.
33. In a machine for running-on knitted web, the combination of a series of hooks for engaging the stitches to be transferred, a carrier upon which said hooks are pivotally mounted, a grid for guiding the hooks during their swinging movement, fingers for discharging the stitches from the hooks, said fingers being contained in slots in the bars of the grid, and means for retaining the fingers in said slots.
34. In a machine for running-on knitted web, the combination of a series of hooks for engaging the stitches to be transferred, a carrier upon which said hooks are pivotally mounted, a grid for guiding the hooks during their swinging movement, fingers for discharging the stitches from the hooks, said fingers being contained in slots in the bars of the grid, and means for retaining the fingers in said slots, said fingers having projections thereon and the retainer being recessed to receive said projections.
35. In a machine for running-on knitted web, the combination of a series of swinging hooks for engaging the stitches to be transferred, a carrier upon which said hooks are pivotally mounted, and an expander for acting upon the rear faces of the hooks and projecting the same, said rear faces of the hooks having a cam formation whereby the final movement of the expander will permit a retraction of the hooks.
36. In a machine for running-on knitted web, the combination of a series of swinging

- hooks for engaging the stitches to be transferred, a carrier upon which said hooks are pivotally mounted, an expander for acting upon the rear faces of the hooks and projecting the same, said rear faces of the hooks having a cam formation whereby the final movement of the expander will permit a retraction of the hooks, and yielding means for effecting such retraction.
- 10 37. In a machine for running-on ribbed knitted web, the combination of a support for the web, means for engaging the stitches to be transferred, and then drawing the web forward, and bits for engaging the ribs of the web and guiding it during such forward movement.
- 20 38. In a machine for running-on ribbed knitted web, the combination of a support for the web, means for engaging the stitches to be transferred, and then drawing the web forward, and bits for engaging the ribs of the web and guiding it during such forward movement, said bits having portions for engaging a welt on the knitted web.
- 25 39. In a machine for running-on ribbed knitted web, the combination of a support for the web, means for engaging the stitches to be transferred, and then drawing the web forward, with bits for engaging the ribs of the web and guiding it during such forward movement, said bits having portions for engaging a welt on the knitted web, and means for imparting forward movement to the bits independently of the stitch-engaging devices.
- 35 40. In a machine for running-on knitted web, the combination of a beveled support over which the knitted web is drawn, and a pusher for engaging a welt on the web and moving the same forwardly, said pusher being beveled to correspond with the bevel of the support.
- 40 41. In a machine for running-on ribbed knitted web, the combination of a beveled support over which the knitted web is drawn, and bits between which the ribs of the web pass, said bits having corresponding beveled portions.
- 45 42. In a machine for running-on ribbed knitted web, the combination of a beveled support over which the web is drawn, bits between which the ribs of the web are caused to pass, and means for positively controlling the radial position of said bits in respect to the support for the web to accord with varying thicknesses of web.
- 50 43. In a machine for running-on knitted web, the combination of a support over which the web is drawn, a pusher for engaging a welt on the web and moving the same forwardly, and means for positively controlling the radial relation of said pusher in respect to the support for the web to accord with varying thicknesses of web.
- 55 44. In a machine for running-on ribbed knitted web, the combination of a support over which the web is drawn, bits between which the ribs of the web are caused to pass, said bits having portions for engaging a welt on the web, and means for positively controlling the radial relation of said welt-engaging portions of the bits in respect to the support for the web to accord with varying thicknesses of web.
- 60 45. In a machine for running-on knitted web, the combination of a support over which the web is drawn, and a pusher for engaging a welt on the web and moving the same forwardly, the web support being correspondingly movable.
- 65 46. In a machine for running-on knitted web, the combination of a support over which the web is drawn, a pusher for engaging a welt on the web and moving the same forwardly, and means whereby corresponding movement is simultaneously imparted to the web support.
- 70 47. In a machine for running-on knitted web, the combination of a support over which the web is drawn, a pusher for engaging a welt on the web and moving the same forwardly, and means passing longitudinally through the web support whereby corresponding movement is simultaneously imparted to the latter.
- 75 48. In a machine for running-on ribbed knitted web, the combination of a support over which the web is drawn, bits between which the ribs of the web are caused to pass, said bits having portions for engaging a welt on the web, and means for moving the bits to push the web forwardly, the web support being correspondingly movable.
- 80 49. In a machine for running-on ribbed knitted web, the combination of a support for the web, bits between which the ribs of the web are caused to pass, said bits having portions for engaging a welt on the web, means for moving said bits so as to cause them to push upon the welt, and means whereby corresponding movement is simultaneously imparted to be web support.
- 85 50. In a machine for running-on knitted web, the combination of a web support, a pusher for engaging a welt on the web and moving the same forwardly, and means independent of the web support for pressing the web against the inner side of said pusher.
- 90 51. In a machine for running-on knitted web, the combination of a web support, a pusher for engaging a welt on the web and moving the same forwardly, means independent of the web support for pressing the web against the inner side of said pusher and means for adjusting said presser in respect to the pusher to accommodate different thicknesses of web.

52. In a machine for running-on ribbed knitted web, the combination of a web support, bits between which the ribs of the web are caused to pass, and means independent of the web support for pressing the web against the inner sides of said bits. 5
53. In a machine for running-on ribbed knitted web, the combination of a support for the web, bits between which the ribs of the web are caused to pass, means independent of the web support for pressing the web against the inner sides of said bits, and means for adjusting said presser in respect to the bits to accommodate different thicknesses of web. 10
54. In a machine for running-on ribbed knitted web, the combination of a support for the web, guide bits between which the ribs of the web are caused to pass, means for engaging the stitches of the web and drawing the same forwardly and bits bearing a fixed relation to the web-guiding bits and serving to register the stitch-engaging devices in respect to the latter. 15
55. In a machine for running-on knitted web, the combination of a support for the web, a pusher for engaging a welt on the web and moving the same forwardly, and means including an adjustable wedge for varying the radial relation of the welt-engaging pusher in respect to the web support to accord with different thicknesses of web. 20
56. In a machine for running-on ribbed knitted web, the combination of a support for the web, bits between which the ribs of the web are caused to pass, said bits being slotted to form spring fingers for engaging a welt on the web, and means for varying the radial relation of these spring fingers in respect to the web support to accord with different thicknesses of web. 25
57. In a machine for running-on ribbed knitted web, the combination of a support for the web, bits between which the ribs of the web are caused to pass, said bits being slotted to form spring fingers for engaging a welt on the web, and means for varying the radial relation of these spring fingers in respect to the web support to accord with different thicknesses of web, said means including an adjustable wedge for acting upon the backs of the fingers. 30
58. In a machine for running-on knitted web, the combination of a support for the web, means for moving the web over said support, a cutting knife for the web, means for moving said knife into and out of cutting relation with the web, and means for varying the depth of cut. 35
59. In a machine for running on knitted web, the combination with a support for the web, of means for engaging the stitches of the web and moving it, a cutting knife for severing the web, means for accurately adjusting the web in respect to said knife, 65 and means for moving the cutting knife into and out of engagement with the web. 60
60. In a machine for running on knitted web, the combination with a support for the web, of means for engaging the stitches of the web, means for moving the stitch engaging means and the web longitudinally of said support, a cutting knife for said web, means for moving the knife into and out of cutting engagement with the web, 75 and means for carrying said knife around the web. 70
61. In a machine for running on knitted web, the combination with a support for the web, of means for engaging the stitches of the web, means for moving the stitch engaging means and the web longitudinally of said support, a revoluble knife for cutting the web, means for accurately adjusting the web in relation to said knife, means for rotating said knife, and means for bringing said knife into engagement with said web. 80
62. In a machine for running on knitted web, the combination with a support for the web, of means for engaging the stitches of the web, means for moving the stitch engaging means and web after the stitches of the web are engaged, a cutting knife for the web, means for moving said knife into and out of cutting relations with said web, means 90 for carrying said knife around the web and means for arresting the carrying means at the end of a single rotation around the web. 95
63. In a machine for running on knitted web, the combination with a support for the web, of means for engaging the stitches, means to move the stitch engaging means and thereby moving the web over the web support, a cutting knife, a carrier for carrying the knife around the axis of support, 100 said knife movably mounted on said carrier, means for moving the carrier and means for arresting its movement when the knife has made one entire revolution 105 around the web. 110
64. In a machine for running on knitted web, the combination with a support for the web having a reduced portion, a brush portion located in said reduced portion, a cutting knife, means for carrying said knife 115 around the said support and means for moving said knife toward and from the brush portion of said support. 115
65. In a machine for running on knitted web, the combination of a support for the web having a brush portion, of a cutting knife, a carrier for carrying said knife around said support, means for moving said knife inward to and out of cutting position and means for varying the extent of the inward movement of the knife. 120
66. In a machine for running-on knitted web, the combination of a support for the 125

- web, means for moving the web over said support, a cutting knife for the web, a knife-carrier rotatable around the axis of the web support, and a knife-mount pivoted upon said carrier and movable in a plane parallel with the face of the same for swinging the knife into and out of cutting relation with the web.
67. In a machine for running-on knitted web, the combination of a support for the web, means for moving the web over said support, a cutting knife for the web, a carrier rotatable around the axis of the web support, a knife-mount pivoted upon said carrier and movable to carry the knife into and out of cutting relation with the web, and a driving shaft for the knife concentric with the pivotal axis of said knife-mount.
68. In a machine for running on knitted web, the combination with a support for a knitted web having a brush portion, means for engaging the web over said brush portion, means for moving said stitch engaging means and the web longitudinally of said support, a revoluble cutting knife, means for moving the said knife into cutting position over said brush portion, and means for revolving said knife, and carrying the same around the brush portion of said support.
69. In a machine for running-on knitted web, the combination of a support for the web, means for moving the web over said support, a rotatable cutting knife for the web, a knife-carrier, means for rotating the same around the axis of the web support, means for moving the knife upon its carrier to cause it to engage or disengage the web, and means whereby the knife-shaft is rotated in any position of adjustment of the knife on its carrier.
70. In a machine for running-on knitted web, the combination of a support for the web, means for moving the web over said support, a cutting knife for the web, a knife-carrier rotatable about the axis of the web support, a knife-mount pivoted upon said carrier, and means whereby said knife-mount is caused to turn on its pivotal axis to move the knife into and out of cutting relation with the web.
71. In a machine for running-on knitted web, the combination of a support for the web, means for moving the web over said support, a cutting knife, a knife-mount, a rotatable carrier upon which the knife-mount is pivotally supported, a toothed member on said knife-mount, and a toothed member meshing therewith and movable independently of the knife-carrier.
72. In a machine for running-on knitted web, the combination of a support for the web, means for moving the web over said support, a rotary cutting knife, means for rotating the same, a knife-mount, a rotatable carrier upon which the knife-mount is pivotally supported, a toothed member on said knife-mount, and a toothed member meshing therewith and movable independently of the knife-carrier.
73. In a machine for running-on knitted web, the combination of a support for the web, means for moving the web over said support, a web cutting knife, a rotatable carrier therefor, and means for arresting the rotation of said carrier when it has completed one or more rotations.
74. In a machine for running-on knitted web, the combination of a support for the web, means for moving the web over said support, a web cutting knife, a rotatable carrier therefor, and means for limiting the rotative movements of said carrier, said means comprising a driving device for the carrier, a clutch and means on the knife-carrier for operating said clutch.
75. In a machine for running-on knitted web, the combination of a support for the web, means for moving the web over said support, a web cutting knife, a carrier therefor, and means for limiting the rotative movement of said carrier, said means comprising a driving device for the carrier, a clutch, means on the knife-carrier for operating said clutch, and means for throwing said clutch-operating device into and out of operative relation with the clutch.
76. In a machine for running-on knitted web, the combination of a support for the web, means for moving the web over said support, a web cutting knife, a carrier upon which the knife is mounted so as to move into and out of operative relation with the web, and means for actuating the knife-mount in advance of the rotation of the knife-carrier.
77. In a machine for running-on knitted web, the combination of a support for the web, means for moving the web over said support, a cutting knife for the web, a rotatable carrier for said knife, means for moving the knife on said carrier into and out of cutting relation with the web, and means for operating said knife-moving device in advance of the movement of the knife-carrier, and then clutching it to said knife-carrier.
78. In a machine for running-on knitted web, the combination of a support for the web, means for moving the web over said support, a cutting knife for the web, a rotatable carrier for said knife, means for moving the knife on said carrier into and out of cutting relation with the web, means for operating said knife-moving device in advance of the movement of the knife-carrier, and then clutching it to said knife-carrier, and means for shifting said clutch point to vary the extent of inward movement of the knife.
79. In a machine for running-on knitted web, the combination of a support for the web, means for moving the web over said support, a cutting knife for the web, a rotatable carrier for said knife, means for moving the knife on said carrier into and out of cutting relation with the web, means for operating said knife-moving device in advance of the movement of the knife-carrier, and then clutching it to said knife-carrier, and means for shifting said clutch point to vary the extent of inward movement of the knife.

- web, the combination of a support for the web, means for moving the web over said support, a cutting knife for the web, a rotatable carrier for said knife, means for moving the knife on said carrier into and out of cutting relation with the web, means for operating said knife-moving device in advance of the movement of the knife-carrier and then clutching it to said carrier, and means for automatically releasing said clutch when the knife-carrier has completed its rotative movement.
80. In a machine for running-on knitted web, the combination of a support for the web, means for moving the web over said support, a cutting knife, a knife-mount movable to carry the knife into and out of cutting relation with the web, a spring for normally retaining it out of such cutting relation, means for moving it into such cutting relation and holding it there, and means for automatically releasing it.
81. In a machine for running-on knitted web, the combination of a support for the web, means for moving the web over said support, a cutting knife for the web, a rotatable knife-carrier upon which said cutting knife is mounted so as to move into and out of cutting relation with the web, a spring for normally holding the knife out of such cutting relation, and means acting in opposition to the spring for moving the knife into cutting relation with the web.
82. In a machine for running-on knitted web, the combination of a support for the web, means for moving the web over said support, a cutting knife for the web, a rotatable knife-carrier upon which said cutting knife is mounted so as to move into and out of cutting relation with the web, a spring for normally holding the knife out of such cutting relation, means acting in opposition to the spring for moving the knife into cutting relation with the web, and means for retaining the knife in such cutting relation.
83. In a machine for running-on knitted web, the combination of a support for the web, means for moving the web over said support, a cutting knife for the web, a rotatable knife-carrier upon which said cutting knife is mounted so as to move into and out of cutting relation with the web, a spring for normally holding the knife out of such cutting relation, means acting in opposition to the spring for moving the knife into cutting relation with the web, means for retaining the knife in such cutting relation, and means for automatically releasing such retaining device and permitting the spring to act to restore such retaining device and permitting the spring to act to restore the knife to inoperative position.
84. In a machine for running-on knitted web, the combination of a support for the web, means for moving the web over said support, a cutting knife for a web, a carrier for said knife, rotating mechanism for said carrier including a clutch, a tripping device for said clutch mounted on the knife-carrier, and a bar having means for moving said tripping device out of engagement with the clutch.
85. In a machine for running-on knitted web, the combination of a support for the web, means for moving the web over the support, a web-cutting knife, a carrier upon which said knife is mounted so as to move into and out of cutting relation with the web, means for thus moving the knife, a driving device for the knife-carrier having a clutch member, a clutch-tripping device on the carrier, and a bar having means for controlling both the operation of the knife-moving device and the operation of the clutch-tripper.
86. In a machine for running-on knitted web, the combination of a support for the web, means for moving the web over said support, a web-cutting knife, a carrier upon which said knife is mounted so as to move into and out of cutting relation with the web, a moving device for the knife, a driving device for the knife-carrier having a clutch member, a clutch-tripping device on the carrier, and a bar having means for controlling both the operation of the knife-moving device and the operation of the clutch-tripper, said means being so disposed that the knife-moving device will be actuated in advance of the clutch tripper.
87. In a machine for running-on knitted web, the combination of a support for the web, means for moving the web over said support, a web-cutting knife, a carrier therefor on which the knife can move into and out of cutting relation with the web, a knife-moving device having means for connecting it with the knife carrier, a driving device for said carrier having a clutch member, a clutch-tripping device on the carrier, and a bar having means for operating said clutch-tripper and for releasing the connection between the knife-moving device and the knife-carrier.
88. In a machine for running-on knitted web, the combination of a support for the web, means for moving the web over said support, a web-cutting knife, a carrier therefor on which the knife can move into and out of cutting relation with the web, a knife-moving device having means for connecting it with the knife-carrier, a driving device for said carrier having a clutch member, a clutch-tripping device on the carrier, and a bar having means for operating said clutch-tripper, means for adjusting the knife-moving device into position for engagement with the knife-carrier, and means

for releasing the knife-moving device from such engagement.

89. In a machine for running-on knitted web, the combination of a receiver for the transferred stitches, means for engaging the stitches and applying them to said receiver, a web support, a movable carrier for the stitch receiver, and inter-locking members on said carrier and web support.

10 90. In a machine for running-on knitted web, the combination of a receiver for the transferred stitches, means for engaging the stitches and applying them to said receiver, a web support, a movable carrier for the stitch receiver, interlocking members on said carrier and web support, and means for engaging the web support and holding it in position for engagement with its interlocking member.

20 91. In a machine for running-on knitted web, the combination of a support for the web with independent and longitudinally separated means for engaging the web and moving the same forward over its support.

25 92. In a machine for running-on knitted web, the combination of a support for the web, means for engaging the stitches of said web and drawing the same forward over the support, and a separate web-engaging device movable with said stitch-engaging device.

30 93. In a machine for running-on knitted web, the combination of a support for the web, means for engaging the stitches of said web and drawing the same forward over the support, a supplementary web-engaging device movable with said stitch-engaging device, and means for disengaging said supplementary device from the web on its rear-

ward movement.

94. In a machine for running-on knitted web, the combination of a support for the web, a stitch-engaging device, a carrier therefor having movement in respect to the web, a supplementary engaging device for the web, and a connection between said supplementary engaging device and said carriage.

95. In a machine for running-on knitted web, the combination of a support for the web, devices for engaging the same at longitudinally separated points, and means for simultaneously moving said devices to feed the web over the support.

55 96. In a machine for running-on knitted web, the combination of a support for the web, stitch-engaging devices movable to carry the web over the support, a supplementary web-engaging device comprising 60 clamping jaws for the web, a carrier therefor, and clamp-actuating means movable independently of said carrier.

97. In a machine for running-on knitted web, the combination of a support for the web, stitch-engaging devices movable to

carry the web over the support, a supplementary web-engaging device comprising clamping jaws for the web, a carrier therefor, and means for actuating said clamping jaws in advance of the movement of the carrier in either direction.

98. In a machine for running-on knitted web, the combination of a support for the web, a clamping device therefor, a frictionally retarded slide carrying said clamping device, and means for opening and closing said clamping device.

99. In a machine for running-on knitted web, the combination of a support for the web, a clamping device therefor, a frictionally retarded slide carrying said clamping device, and means for opening and closing said clamping device, said means also serving to impart reciprocating movement to the slide.

100. In a machine for running-on knitted web, the combination of a web support, clamping devices for the web comprising a pair of levers, a carrier therefor, movable in the direction of movement of the web, and means for moving said carrier through the medium of the clamping levers.

101. In a machine for running-on knitted web, the combination of a web support, clamping devices for the web comprising a pair of levers, a carrier therefor, movable in the direction of movement of the web, and means for moving said carrier through the medium of the clamping levers, said means including devices for closing the levers before the forward movement of the carrier and opening them before the rearward movement of the carrier.

102. In a machine for running-on knitted web, the combination of a support for the web, with means for effecting the forward movement of the web over said support by engagement with stitches of the web, and means for further moving the web by engagement with a welt thereon.

103. In a machine for running-on knitted web, the combination of a support for the web with means comprising stitch-engaging devices and welt-engaging devices for effecting forward movement of the web over the support, and means for operating the stitch-engaging devices before the operation of the welt-engaging devices, so as to draw the welt into position in advance of the latter.

104. In a machine for running-on knitted web, the combination of a support for the web, means, including stitch-engaging devices and welt-engaging devices, for effecting forward movement of the web over the support, means for cutting an advanced section of web from the remaining portion, and means for operating the welt-engaging devices to adjust the welt to a position in advance of the cutting knife.

105. In a machine for running-on knitted web, the combination of a support for the web, means, including stitch-engaging devices and welt-engaging devices, for moving the web over the support, a cutting device for severing an advanced section of the web from the following section, means for operating the stitch-engaging devices in advance of the welt-engaging devices to bring the welt into position in front of the latter, and means for then actuating the welt-engaging devices to adjust the welt to a position in advance of the cutting knife. 5
106. In a machine for running-on knitted web, the combination of means for engaging the stitches to be transferred, an expander for said engaging means and a two-part carriage, one part carrying the engaging devices and the other part carrying the expander. 10
107. In a machine for running-on knitted web, the combination of means for engaging the stitches to be transferred, means for discharging the stitches from said engaging devices and a two-part carriage one part carrying the engaging devices and the other part carrying the discharging devices. 15
108. In a machine for running-on knitted web, the combination of the stitch-engaging and transferring devices, with a two-part carriage, means for applying power to one part of said carriage to move the same, a temporary locking device for restraining the movement of the other part of the carriage, and an automatic release for said locking device. 20
109. In a machine for running-on knitted web, the combination of the stitch-engaging and transferring devices with a two-part carriage, means for applying power to one part of said carriage, to move the same, a temporary locking device for restraining the movement of the other part of the carriage, and an automatic release for said locking device, operated by the moving member of the carriage. 25
110. In a machine for running-on knitted web, the combination of the stitch-engaging and transferring devices with a two-part carriage, whose parts are independently movable, and engaging devices on the two parts of the carriage for insuring their proper relation one to the other, when the stitches are being transferred. 30
111. In a machine for running-on knitted web, the combination of the stitch-engaging and transferring devices with a two-part carriage whose parts are independently movable, and engaging devices on the two parts of the carriage for insuring the proper relation of one to the other, said engaging devices having cam-like portions whereby longitudinal movement of one member of the carriage in respect to the other will be caused by movement in a different plane of 35
- one of the engaging devices in respect to the other. 40
112. In a machine for running-on knitted web, the combination of the stitch engaging and transferring devices with a two-part carriage having engaging members for maintaining the parts of the carriage in proper relation to one another, one of said engaging members being mounted upon a spring-pressed carrier. 45
113. In a machine for running-on knitted web, the combination of the stitch engaging and transferring devices with a two-part carriage, means for imparting movement to one part of the carriage, and a spring-pressed connection interposed between the two parts of the carriage when the driven part is approaching the limit of its movement in one direction. 50
114. In a machine for running-on knitted web, the combination of hooks for engaging the stitches to be transferred, bits for discharging the stitches from said hooks, a two-part carriage, one part carrying the bits and the other part carrying the hooks, and a compressible connection between the two members of the carriage, which connection is compressed when the first member of the carriage approaches the limit of its forward movement. 55
115. In a machine for running-on knitted web, the combination of stitch-engaging devices, an expander therefor, means for discharging the stitches from the stitch-engaging devices and a two-part carriage, one part of said carriage having mounted upon it the stitch-engaging devices and the other having mounted upon it the stitch-expanding and discharging devices. 60
116. In a machine for running-on knitted web, the combination of stitch-engaging devices, an expander therefor, means for discharging the stitches from the stitch-engaging devices, a two-part carriage, one part having mounted upon it the stitch-engaging devices and the other part having mounted upon it the expander and the stitch-discharging devices, means for first moving the latter part of the carriage without movement of the part which carries the stitch-engaging devices, then moving both parts of the carriage, and finally moving that part which carries the expander and stitch-discharging devices without moving the part which carries the stitch-engaging devices. 65
117. In a machine for running-on knitted web, the combination of stitch-engaging devices, an expander therefor, means for discharging the stitches from the stitch-engaging devices, a two-part carriage, one part having mounted upon it the stitch-engaging devices and the other part having mounted upon it the expander and the stitch-discharging devices, means for first moving the latter part of the carriage without move- 70

ment of the part which carries the stitch-engaging devices, then moving both parts of the carriage, finally moving that part which carries the expander and stitch-discharging devices without moving the part which carries the stitch-engaging devices, and means for permitting the contraction of the stitch-engaging devices during the final movement.

118. In a machine for running-on knitted web, the combination of means for engaging and transferring the stitches, with a carrier having a plurality of stitch-receiving devices, said carrier being movable so as to bring its stitch-receiving devices in succession into position for receiving the stitches from the transfer mechanism.

119. In a machine for running-on knitted web, the combination of means for engaging and transferring the stitches, with a carrier having a plurality of stitch-receiving devices, said carrier being movable so as to bring its stitch-receiving devices in succession into position for receiving the stitches from the transfer mechanism, and means for imparting such intermittent movements to the carrier.

120. In a machine for running-on knitted web, the combination of means for engaging and transferring the stitches, with a rotary turret carrying a plurality of stitch-receivers, said turret being rotatable to bring its stitch-receivers in succession into position to receive the stitches from the transfer devices.

121. In a machine for running-on knitted web, the combination of means for engaging and transferring the stitches, with a rotary turret carrying a plurality of stitch-receivers, said turret being rotatable to bring its stitch-receivers in succession into position to receive the stitches from the transfer devices, and means for effecting intermittent movements of partial rotation of said turret.

122. In a machine for running-on knitted web, the combination of stitch-engaging and transfer devices, a movable carriage therefor, a holder having a plurality of stitch-receivers thereon, and means interposed between said holder and the carriage for moving the holder so as to bring its receivers in succession into position for receiving the stitches from the transfer devices.

123. In a machine for running-on knitted web, the combination of stitch-engaging and transfer devices, a movable carriage therefor, a rotatable turret having a plurality of stitch-receivers thereon, and a connection between said turret and the carriage whereby intermittent movements of partial rotation are imparted to the turret.

124. In a machine for running-on knitted web, the combination of stitch-engaging and transfer devices, a stitch-receiver, a holder for said stitch-receiver, and automatic

means for locking the receiver to the holder 65 and releasing it therefrom.

125. In a machine for running-on knitted web, the combination of stitch-engaging and transfer devices, a stitch-receiver, a holder whereby said stitch-receiver can be moved 70 into or out of operative relation with said transfer devices, and means operated by the movement of the holder for releasing the stitch receiver therefrom.

126. In a machine for running-on knitted web, the combination of stitch-engaging and transfer devices, a stitch-receiver, a holder whereby said stitch-receiver can be moved 75 into or out of operative relation with said transfer devices, and means operated by the application of the receiver to the holder for locking the same together.

127. In a machine for running-on knitted web, the combination of stitch-engaging and transfer devices, a stitch-receiver, a holder 85 whereby said stitch-receiver can be moved into or out of operative relation with said transfer devices, means, operated by the application of the receiver to the holder, for locking the same together, and means operated by the movement of the holder for releasing the receiver therefrom.

128. In a machine for running-on knitted web, the combination of stitch-engaging and transfer devices, a stitch-receiver, a holder 95 therefor, and automatic means for discharging the stitch-receiver from said holder.

129. In a machine for running-on knitted web, the combination of stitch-engaging and transfer devices, a stitch-receiver, a holder 100 therefor movable to carry the stitch-receiver into and out of operative relation with the transfer devices, and means operated by the movement of the holder for effecting the discharge of the receiver therefrom. 105

130. In a machine for running-on knitted web, the combination of stitch-engaging and transfer devices, a plurality of stitch-receivers, a rotary turret carrying the same, and means whereby the rotary movement of the 110 turret is caused to effect the release of the stitch-receivers therefrom.

131. In a machine for running-on knitted web, the combination of stitch-engaging and transfer devices, a plurality of stitch receivers, a rotary turret on which said receivers are mounted and means operated by the movement of the turret for discharging the stitch-receivers therefrom. 115

132. In a machine for running-on knitted web, the combination of stitch-engaging and transfer devices, a stitch-receiver, a movable carrier therefor, means for locking the receiver to the carrier, and means, operated by the movement of the carrier, for effecting 120 both the release of the stitch-receiver and its discharge from the carrier.

133. In a machine for running-on knitted

web, the combination of stitch-engaging and transfer devices, a stitch-receiver, a carrier therefor, and a movable ring on said carrier having a bolt for engaging the stitch-receiver and locking it to the carrier.

134. In a machine for running-on knitted web, the combination of stitch-engaging and transfer devices, a stitch-receiver, a carrier therefor, a movable ring on said carrier having a bolt for engaging the stitch-receiver and locking it to the carrier, and a spring for normally holding said bolt in locking position.

135. In a machine for running-on knitted web, the combination of stitch-engaging and transfer devices, a stitch-receiver, a carrier therefor, a movable ring on said carrier having a bolt for engaging the stitch-receiver and locking it to the carrier, and a spring for normally holding said bolt in locking position, the bolt having a beveled portion whereby it is moved out of locking position by engagement with the stitch-receiver.

136. In a machine for running-on knitted web, the combination of stitch-engaging and transfer devices, a stitch-receiver, a carrier therefor, and a cam ring movable on said carrier and acting upon the stitch-receiver to eject it from the carrier.

137. In a machine for running-on knitted web, the combination of stitch-engaging and transfer devices, a stitch-receiver, a carrier therefor, a cam ring movable on said carrier, and acting upon the stitch-receiver to eject it from the carrier, and a spring for normally retaining said cam ring in retracted position.

138. In a machine for running-on knitted web, the combination of the stitch-receiver, a carrier therefor having a projecting stem, and means for effecting discharge of the receiver from the carrier, said means including a guide for directing the receiver clear of said projecting stem.

139. In a machine for running-on knitted web, the combination of the stitch-receiver, a carrier therefor having a projecting stem, and means for effecting discharge of the receiver from the carrier, said means including an inclined guide down which the receiver can slide, and a pusher for moving the receiver onto said guide.

140. In a machine for running-on knitted web, the combination of stitch-engaging and transfer devices, a stitch-receiver, a carrier for moving the stitch-receiver into and out of operative relation with the stitch-engaging and transfer devices, and means for automatically feeding stitch-receivers to said carrier.

141. In a machine for running-on knitted web, the combination of stitch-engaging and transfer devices, a stitch-receiver, a carrier for moving the stitch-receiver into and out

of operative relation with the stitch-engaging and transfer devices, means for automatically feeding stitch-receivers to said carrier, and means for automatically locking said stitch-receivers to said carrier.

142. In a machine for running-on knitted web, the combination of stitch-engaging and transfer devices, a stitch-receiver, a carrier for moving the stitch-receiver into and out of operative relation with the stitch-engaging and transfer devices, means for automatically feeding stitch-receivers to said carrier, means for automatically locking said stitch-receivers to said carrier, and means for automatically releasing the stitch-receivers therefrom.

143. In a machine for running-on knitted web, the combination of stitch-engaging and transfer devices, a stitch receiver, a carrier for moving the stitch-receiver into and out of operative relation with the stitch-engaging and transfer devices, means for automatically feeding stitch-receivers to said carrier, and means for automatically discharging the stitch-receivers from the carrier.

144. In a machine for running-on knitted web, the combination of stitch-engaging and transfer devices, a stitch-receiver, a carrier for moving the stitch-receiver into and out of operative relation with the stitch-engaging and transfer devices, means for automatically feeding stitch-receivers to said carrier, means for automatically releasing the receivers from the carrier, and means for automatically discharging the receivers from the carrier.

145. In a machine for running-on knitted web, the combination of stitch-engaging and transfer devices, a stitch receiver, a carrier therefor, operable to move the stitch-receiver into and out of operative relation with the stitch-engaging and transfer devices, and means for automatically feeding a stitch-receiver to said carrier when it is out of operative relation with said stitch-engaging and transfer devices.

146. In a machine for running-on knitted web, the combination of stitch-engaging and transfer devices, a stitch-receiver, a carrier therefor, operable to move the stitch-receiver into and out of operative relation with the stitch-engaging and transfer devices, means for automatically feeding a stitch-receiver to the carrier when it is in one of such inoperative relations, and means for automatically discharging the stitch-receiver from the carrier when it is in another of such inoperative relations.

147. In a machine for running-on knitted web, the combination of stitch-engaging and transfer devices, a carrier having a plurality of holders, each for the reception of a stitch-receiver, means for moving said carrier, and

means for automatically feeding stitch-receivers to the successive holders therefor.

148. In a machine for running-on knitted web, the combination of stitch-engaging and transfer devices, a movable carrier having a plurality of holders each for the reception of a stitch-receiver, a magazine containing said stitch-receivers, and means for automatically feeding the receivers from the magazine onto the successive holders of the carrier as they are moved into line with the mouth of the magazine.

149. In a machine for running-on knitted web, the combination of stitch-engaging and transfer devices, stitch-receivers, a movable holder for the latter, a magazine containing a series of such receivers, catches for retaining the same in the magazine, and means for automatically releasing said catches when the magazine and holder are brought into operative relation with one another.

150. In a machine for running-on knitted web, the combination of stitch-engaging and transfer devices, stitch-receivers, a movable holder for the latter, a magazine containing a series of such receivers, catches for retaining the same in the magazine, means for automatically releasing said catches when the magazine and holder are brought into operative relation with one another, and means for feeding the receivers through the magazine.

151. In a machine for running-on knitted web, the combination of a magazine, containing a series of stitch-receivers, a movable holder to which said stitch-receivers are applied in succession, and means for moving the magazine from and toward the holder in order to permit movement of the latter.

152. In a machine for running-on knitted web, the combination of a magazine containing a series of stitch-receivers, a movable holder to which said stitch-receivers are applied in succession, means for moving the magazine from and toward the holder in order to permit movement of the latter, and means for feeding the stitch-receivers forwardly in the magazine.

153. In a machine for running-on knitted web, the combination of stitch-engaging and transfer devices, a carriage upon which they are mounted, a magazine for containing a series of stitch-receivers, a movable holder for conveying said stitch-receivers from the magazine to the stitch-engaging and transfer devices, and means whereby the movements of the carriage are caused to effect movement of said magazine into and out of operative relation to the said holder.

154. In a machine for running-on knitted web, the combination of stitch-engaging and transfer devices, a carriage upon which they are mounted, a magazine for containing a series of stitch-receivers, a movable holder

for conveying said stitch-receivers from the magazine to the stitch-engaging and transfer devices, and means whereby movement of the carriage is caused to effect movement of the magazine into and out of operative relation with the holder, and movement of the latter into and out of operative relation with the magazine and with the stitch-engaging and transfer devices.

155. In a machine for running-on knitted web, the combination of a movable holder, a magazine having a series of stitch-receivers therein, means for feeding the stitch-receivers forwardly through the magazine, means for preventing turning movement of the stitch-receivers in the magazine, and means for delivering said stitch-receivers in succession to the holder.

156. In a machine for running-on knitted web, the combination of a rotatable turret having thereon a plurality of holders, a magazine containing a series of stitch-receivers, and means for automatically delivering the stitch receivers in succession to the holders therefor on the turret as the latter is rotated in front of the magazine.

157. In a machine for running-on knitted web, the combination of a rotatable turret having thereon a plurality of holders, a magazine containing a series of stitch-receivers, means for automatically delivering the stitch-receivers in succession to the holders therefor on the turret as the latter is rotated in front of the magazine, and means for moving the magazine from and toward the turret.

158. In a machine for running-on knitted web, the combination of stitch-engaging and transfer devices, a rotating turret having thereon holders for a plurality of stitch-receivers, which can be presented in succession to the transfer devices by imparting movements of partial rotation to said turret, and means for arresting the movement of the turret after each partial rotation of the same.

159. In a machine for running-on knitted web, the combination of stitch-engaging and transfer devices, a rotating turret having thereon holders for a plurality of stitch-receivers, means for imparting movements of partial rotation to said turret, and means for arresting the movement of the turret after each partial rotation of the same, said means being automatically released on the next application of power to turn the turret.

160. In a machine for running-on knitted web, the combination of stitch-engaging and transfer devices, a movable carriage on which said devices are mounted, a stitch-receiver, a movable holder whereby said stitch-receiver is moved into and out of operative relation with the stitch-engaging and transfer devices, and means whereby the

- carriage is caused to impart movement to said holder.
161. In a machine for running-on knitted web, the combination of stitch-engaging and transfer devices, a movable carriage therefor, with a turret having holders for a plurality of stitch-receivers, and means whereby movement of the carriage is transmitted to said turret.
162. In a machine for running-on knitted web, the combination of stitch-engaging and transfer devices, a movable carriage on which said devices are mounted, a turret having holders for a plurality of stitch-receivers, and a rack, a spur pinion, a pawl and a ratchet wheel interposed between said carriage and turret, whereby the turret will remain stationary on the forward movement of the carriage but will be partially rotated on the rearward movement of the same.
163. In a machine for running-on knitted web, the combination of stitch-engaging and transfer devices, a carriage upon which the same are mounted, a rotary turret having holders for a plurality of stitch-receivers, a magazine for delivering stitch-receivers to said turret in succession, a connection between the carriage and the turret for effecting rotation of the latter, and a connection between the carriage and the magazine for moving the latter out of the way of the turret before the latter begins its rotative movement.
164. In a machine for running-on knitted web, the combination of stitch-engaging and transfer devices, a carriage upon which the same are mounted, a stitch-receiver, a movable holder whereby said stitch-receiver is carried into and out of operative relation with the stitch-engaging and transfer devices, and a connection whereby movement of the carriage is imparted to said holder, said connection having as an element an automatic trip whereby it is released from the carriage during the movement of the latter.
165. In a machine for running-on knitted web, the combination of stitch-engaging and transfer devices, a receiver for the transferred stitches, and power-actuated means for effecting the transfer of the stitches from the stitch-engaging devices to the stitch-receiver.
166. In a machine for running on knitted web, the combination with stitch engaging means of stitch receiving devices, means for moving the stitch engaging means toward the receiving devices after the stitches have been engaged, said moving means providing for a dwell in said movement, a cutter and means for actuating said cutter during the dwell in the movement of the stitch engaging means.
167. In a machine for running on knitted web, the combination with a support for the web, stitch engaging means for engaging and moving the web, and means for engaging a welt on said web and pushing the same longitudinally of said support while the stitch engaging means are free from the web.
168. In a machine for running on knitted web, the combination with a web support having a brush portion, of stitch engaging devices adapted to engage the stitches of the web over said brush portion, and means for engaging a welt on said web and pushing the web over said brush portion.
169. In a machine for running-on knitted web, the combination of stitch-engaging and transfer devices, a receiver for the transferred stitches, and power-actuated means for moving said receiver into and out of operative relation with the transfer devices.
170. In a machine for running-on knitted web, the combination of the stitch-engaging and transfer devices, and a power-actuated endless chain for controlling the operation of the same.
171. In a machine for running-on knitted web, the combination of a support for the web, means for engaging a welt on said web, and pushing the same over the support, and a power-actuated endless chain for controlling the operation of such pusher.
172. In a machine for running-on knitted web, the combination of a support for the knitted web, a knife for cutting the same, means for carrying the said knife around the web, and a power-actuated chain for controlling the operation of said carrier.
173. In a machine for running-on knitted web, the combination of a support for a tubular web with means for moving the web over the support by contact with a welt thereon, said means having a pushing face whose continuity is interrupted by a shoulder.
174. In a machine for running-on knitted web, the combination of a support for a tubular web with means for moving the web over the support by contact with a welt thereon, said means having a helical face whose continuity is interrupted by a shoulder.
175. In a machine for running-on ribbed knitted web, the combination of a support for a tubular web, bits fitting between the ribs of the web and adapted to engage a welt on said web, the bits presenting a pushing face whose continuity is interrupted by a shoulder.
176. In a machine for running-on ribbed knitted web, the combination of a support for a tubular web, bits fitting between the ribs of the web and adapted to engage a welt on said web, the bits presenting a helical pushing face for engaging the welt.

177. In a machine for running-on knitted web, the combination of a support for the web, and means for engaging and lining up a welt on said web, said means including a cam engaging the pusher and movable in a direction transverse to the direction of movement of the pusher.

178. In a machine for running-on knitted web, the combination of a support for the web, means for engaging and lining up a welt on said web, said means including a cam engaging the pusher and movable in a direction transverse to the direction of movement of the pusher, and power-actuated means for operating said cam.

179. In a machine for running-on knitted web, the combination of stitch-engaging and transfer devices, a carriage therefor, means for imparting forward and backward movement to said carriage, and automatic means for effecting reversal in the direction of movement when the carriage is at the forward termination of its travel.

180. In a machine for running-on knitted web, the combination of stitch-engaging and transfer devices, a carriage therefor, means for imparting forward and backward movement to said carriage, and automatic means for effecting reversal in the direction of movement when the carriage is at the rearward termination of its travel.

181. In a machine for running-on knitted web, the combination of stitch-engaging and transfer devices, a carriage therefor, means for imparting forward and backward movement to said carriage, and automatic means for effecting reversal in the direction of movement of the carriage both at the forward and rearward termination of its travel.

182. In a machine for running-on knitted web, the combination of stitch-engaging and transfer devices, a carriage therefor, means for imparting forward and backward movement to said carriage, and an endless chain for operating said means.

183. In a machine for running-on knitted web, the combination of stitch-engaging and transfer devices, a carriage therefor, means for imparting forward and backward movement to said carriage, and an endless chain for operating said means, one run of the chain effecting the forward movement and the other run of the chain effecting the backward movement.

184. In a machine for running-on knitted web, the combination of stitch-engaging and transfer devices, a carriage therefor, a rack on said carriage, a shaft carrying a pinion which engages said rack, means for imparting alternate forward and backward movement to said shaft, and automatic means for reversing the direction of movement of the shaft.

185. In a machine for running-on knitted

web, the combination of stitch-engaging and transfer devices, a carriage therefor, a rack on said carriage, a shaft having a pinion engaging said rack, a second pinion on said shaft, a longitudinally movable rack engaging said second pinion, and power-actuated means for reciprocating the latter rack.

186. In a machine for running-on knitted web, the combination of stitch-engaging and transfer devices, a carriage therefor, a rack on said carriage, a shaft having a pinion engaging said rack, a second pinion on said shaft, a longitudinally movable rack engaging said second pinion, and an endless chain having means for engaging and imparting forward and backward movement to said rack.

187. In a machine for running-on knitted web, the combination of stitch-engaging and transfer devices, a carriage therefor, a rack on said carriage, a shaft having a pinion engaging said rack, a second pinion on said shaft, a rack engaging said pinion, a trigger on said rack, an endless chain having means for engaging said trigger, and means for releasing the trigger from the control of said engaging means.

188. In a machine for running-on knitted web, the combination of stitch-engaging and transfer devices, a carriage therefor, and power-actuated means for imparting a two-stage forward movement to said carriage with a dwell between the successive stages of movement.

189. In a machine for running-on knitted web, the combination of stitch-engaging and transfer devices, a carriage therefor, and power-actuated means for operating said carriage and imparting thereto a two-stage forward movement with a dwell between successive stages, and a single stage rearward movement.

190. In a machine for running-on knitted web, the combination of stitch-engaging and transfer devices, a carriage therefor, a rack on said carriage, a shaft having a pinion for engaging said rack, a second pinion on said shaft, a rack for engaging said pinion, a trigger on said rack, an endless chain having two engaging devices for said trigger, and means for removing the trigger from contact with said engaging devices in succession.

191. In a machine for running-on knitted web, the combination of a support for said web, means for moving the web forward over said support, and a longitudinally fixed member of the machine with which said web support is in engagement while the web is being fed forward over the same and which prevents forward movement of the support with the web.

192. In a machine for running-on knitted web, the combination of a support for the web, stitch-engaging and transfer devices,

for drawing the web forward over said support, and a longitudinally fixed member of the machine with which said web-support engages during the forward movement of 5 said support with the web.

193. In a machine for running-on knitted web, a support for the web comprising two members, one movable longitudinally in respect to the other.

10 194. In a machine for running-on knitted web, a support for the web comprising two members, one movable longitudinally in respect to the other, and means for longitudinally retaining one of said members.

15 195. In a machine for running-on knitted web, the combination of a feed hopper for the stitch-receivers, a holder upon which said stitch-receivers are deposited in succession from the hopper, and a plurality of receivers each having a recessed base for the reception of the projecting portions of the

20 quills of the next receiver.

196. In a machine for running on knitted web, the combination with a support for the 25 web and stitch receiving devices, of stitch engaging devices, each having its stitch engaging portion inclined at an angle to the main body of such device and in a substantially vertical position when engaging the 30 stitches of the web and in a horizontal position when engaging the stitch receiving devices.

197. In a machine for running on knitted web, the combination with a web support 35 and stitch receiving devices, of engaging devices, each having its stitch engaging portion at an angle to the main body thereof and substantially vertical to the web support when engaging the stitches of the web 40 and substantially parallel with the same when engaging the stitch receiving devices.

198. In a machine for running-on knitted web, the combination of stitch-engaging devices, an offset or helical pusher for acting 45 on a welt on the web, and means for causing an offset or helical disposition of said stitch-engaging devices, to accord with the disposition of the slack course of the web.

199. In a machine for running-on knitted 50 web, the combination of means for receiving the stitches of the knitted web, and means for engaging said stitches and applying them to the receiver, one of said means being movable in respect to the other.

55 200. In a machine for running-on knitted web, the combination of means for receiving the stitches to be transferred, and means for engaging said stitches and applying them to the receiving means, whereby when 60 the stitch engaging devices are retracted the stitches will remain upon the receiving devices.

201. In a machine for running-on knitted web, the combination of means for receiving

the stitches to be transferred, means for engaging said stitches and applying them to the receiving means, and means for preventing the withdrawal of the stitches from the receiving means when the stitch-engaging devices are retracted. 65

202. A transerrer for knit fabric comprising among its members a series of transfer levers, and a web support movable past the said transfer levers. 70

203. A transerrer for knit fabric comprising among its members a series of transfer levers, and a web support movable to and fro past said levers. 75

204. A transerrer for knitted fabrics comprising among its members a circular 80 series of transferring levers, and a cylindrical web support movable within the series of levers.

205. A transerrer for knit fabrics comprising a series of transfer levers, a web 85 support movable to and fro past said transfer levers and means for moving the said levers toward and from the said web support.

206. A transerrer for knitted fabric comprising among its members a series of transfer levers, a web support movable past said levers, a device for moving the free ends of the levers away from said support by a positive movement, and means for moving said 95 levers toward said support by an elastic or yielding force at the start and afterward by positive movement. 90

207. A web support for a machine for transferring knit fabric having a plain portion for receiving the main portion of the fabric and a brush portion for receiving the edge to be applied to a knitting machine, said brush portion having its surface raised above the plane of the surface of the main 105 portion of the web support. 100

208. In a machine for transferring tubular knit fabrics, the combination with the web support, of transfer levers to take the loops of the web while the web is supported 110 by the support, said web support having a brush portion to sustain the web at the point at which the levers are forced through the web, substantially as described.

209. In a machine for running on a seam- 115 less knitted web, the combination with stitch receiving means, of means for applying the stitches of a single course to said stitch receiving means, a mandrel for engaging and expanding the web, said mandrel expanding 120 the web only within a short distance of the stitch-engaging point.

210. In a machine of the character disclosed, a set of points operative to deliver the loops at the edge of the end of the 125 fabric to the quills of the transfer, means for causing the fabric to be stretched and drawn out a distance, and means for then cutting

off the stretched-out portion, leaving the same on the transfer.

211. The machine for automatically loading transfers, comprising a plurality of co-operating sets of points which act on the raw edge of the fabric to effect the transfer, and means for then cutting the fabric a distance from said raw edge, as set forth.

In testimony whereof, I have signed my name to this specification, in the presence of 10 two subscribing witnesses.

WALTER D. BUTZ.
